UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed December 22, 1917. Serial No. 208,444.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to a machine for automatically assembling or building heels. More particularly, the invention relates to a heel-building or assembling machine for automatically and progressively building sections of leather lifts and for securing the same to previously and extraneously formed leatherboard heel blocks that are successively fed to the machine to form a complete heel, although the invention is not limited to this general combination since important features thereof are embodied in the various individual mechanisms and devices which act successively on the heel, or part thereof, to secure the final result.

In Letters Patent of the United States No. 1,372,059 granted to me March 22, 1921, there is shown and described a heel assembling machine in which leather lifts are positioned upon and attached to a series of previously formed leatherboard heel blocks. In this machine, however, the leather lifts are assembled by hand and manually placed in suitable arms that transfer the lifts and superpose them upon the intermittently advanced heel blocks, to which they are nailed or otherwise secured.

One of the objects of the present invention is to improve the construction and operation of the prior machine above referred to, and to provide a machine of this type which shall be entirely automatic in its action and which shall function with rapidity and accuracy to produce the desired results.

Another object of the invention is to provide a machine of the above indicated character which shall comprise novel means for building sections of superposed leather lifts, and novel means for attaching such sections to the previously and extraneously formed heel blocks.

A further object of the invention is to

provide means for insuring that the component leather and leatherboard sections are of the proper dimensions before they are attached together.

To these ends, one feature of the machine comprises a series of independent intermittently actuated cars or carriers upon which the leather lifts are progressively superposed in successive assembling stations by the aid of concurrently operative pickers which transfer lifts thereto from a row of magazines or lift-holders. The independence of the several carriers permits any carrier to be individually handled in a manner different from the rest of the carriers. Each carrier is arranged to sustain one or more downwardly projecting pointed members upon which the transferred lifts are impaled by a reciprocating plunger. It has been found convenient in practice to employ the nails, which are used to secure the leather heel-section to the leatherboard heel-section, as the pointed members on which the leather lifts are impaled. A preferred, but not essential, construction of the carriers, therefore, provides for holding a plurality of nails projecting from the face against which the leather lifts are assembled.

Another feature of the machine resides in the means for positioning the previously and extraneously formed leatherboard heel blocks beneath and in registry with the assembled and impaled lifts, and in the mechanism for driving the aforesaid nails free from the carriers and into the heel blocks to hold the component sections together.

A further feature of the invention includes measuring apparatus which serves to separately measure the assembled sections of leather lifts and the leatherboard heel blocks prior to their attachment, and to eject both in case either one varies from its predetermined proper dimension.

Other objects of the invention, and the features of construction and operation by which they are attained, will be readily apparent to those skilled in the art from the following description of the illustrated embodiment of the invention. The invention, in its broader aspects, is not confined to the specific structural details and mode of operation set forth, and the advantages and benefits thereof may be attained by machines

2
differing widely in certain respects from that shown and described. Furthermore, the invention as herein set forth, is not limited to the conjoint use of all its features, 5 and it will be understood from the following description that it is within the scope of the invention to use some features without others or to combine the various features in a different manner than is described as the preferred combination. Therefore, only such 10 limitations should be imposed as are indicated in the appended claims.

The preferred embodiment of the invention is illustrated in the accompanying drawings, in which, Figures 1 and 2 taken together, constitute a plan view of a machine constructed in accordance with the invention; Fig. 3 is a view in side elevation looking at the front of the machine shown in 15 Figs. 1 and 2; Fig. 4 is a view in end elevation looking from right to left in Figs. 1 and 2; Fig. 5 is a view in side elevation of a portion of the machine looking from the back of the machine shown in Figs. 1 and 20 2; Fig. 6 is a view, partially in end elevation and partially in section, of the machine, the section being taken along the line 6—6 of Fig. 2; Fig. 7 is a view, partially in side elevation and partially in section, along the 25 line 7—7 of Fig. 1, showing particularly a portion of one of the lift magazines and slideable picker members, the picker member being illustrated in the act of removing one 30 of the lifts from the magazine; Fig. 8 is a view, partially in side elevation and partially in section, taken along the line 8—8 of Fig. 2, and illustrating particularly the relative positions of a carrier, a picker member, the pasting and impaling apparatus, and the 35 lift supporting devices, when the pasting and impaling apparatus occupies its raised position after having impaled the last lift upon the nails of the carrier; Fig. 9 is an enlarged plan view of the upper face of a 40 portion of one of the lift magazines; Fig. 45 10 is an enlarged sectional view, on the line 10—10 of Fig. 9, of one of the lift magazines; Fig. 11 is an enlarged view, partially in section and partially in side elevation, of 50 the gripping fingers of one of the picker members, the section being taken along the line 11—11 of Fig. 12; Fig. 12 is a plan view, partially in section, of a part of the machine, showing particularly the picker members, 55 lift-supporting fingers and certain of the carriers occupying a nail-loading position, a measuring position and a nailing position, certain of the parts being removed for the sake of clearness; Fig. 13 is an enlarged 60 sectional view, taken on the line 13—13 of Fig. 7, and showing certain parts of one of the picker members; Fig. 14 is an enlarged plan view of one of the lift carriers; Fig. 15 is an enlarged sectional view, on the line 65 15—15 of Fig. 14; Fig. 16 is an enlarged

view in the side elevation of the heel block transferring carriage; Fig. 17 is a bottom plan view of the nail gripping devices embodied in the several carriers; Fig. 18 is an enlarged view, partially in section and partially in elevation, of the pasting and lift-impaling apparatus, and lift-supporting fingers, the section being taken on the line 18—18 of Fig. 19; Fig. 19 is an enlarged 70 sectional view, along the line 19—19 of Fig. 18, showing the pasting apparatus and driving clutch; Fig. 20 is a view in side elevation, looking from left to right, of the apparatus shown in Fig. 19; Fig. 21 is an enlarged plan view of the pasting and lift-impaling apparatus, and driving clutch shown in Figs. 18, 19 and 20; Fig. 22 is a view, 75 partially in section and partially in elevation, of a portion of the machine, illustrating particularly the nail loading device and its actuating mechanism, the section being taken along the line 22—22 of Fig. 1; Fig. 23 is an enlarged view in end elevation of a portion of the machine as illustrated in Fig. 4, and showing particularly a lift carrier and the heel 80 block transferring carriage in its raised position preparatory for the nailing operation; Fig. 24 is an enlarged plan view of the heel block transferring carriage shown in Fig. 16; Fig. 25 is an enlarged view, partially in section and partially in side elevation, of a portion of the right-hand end of the machine, and illustrating especially the heel 85 block transferring carriage, the nailing mechanism and the mechanism for raising the carriage into its nailing position, the section being taken along the line 25—25 of Fig. 4; Fig. 26 is a view partially in section and partially in end elevation, of the machine, the section being taken along the line 90 26—26 of Fig. 3, and illustrating particularly the measuring mechanism; Fig. 27 is a detail plan view of a portion of the measuring mechanism shown in Fig. 26, and looking downward from the line 27—27; Fig. 28 is a view in elevation of a portion of the 95 measuring mechanism shown in Fig. 26; Fig. 29 is an enlarged sectional view of a portion of the measuring mechanism, taken on the line 29—29 of Fig. 28; Fig. 30 is a 100 view in side elevation of a portion of the measuring mechanism shown in Fig. 28, and Fig. 31 is a plan view, partially in section, of a portion of the measuring mechanism, taken on the line 31—31 of Fig. 28. 105

Referring to the drawings, the machine shown comprises in general, a frame 32 for supporting the various component elements embodied in the machine; a plurality of 110 lift magazines or holders 34 for containing stacks of leather lifts L of graded characteristics; a plurality of independent individually handled carriers or cars 36 upon which leather lifts are progressively as- 115

sembled in the form of heel piles and which carriers are actuated step-by-step through a nail loading station, a plurality of lift-assembling stations, a measuring station and 5 a nailing station; a plurality of supporting and guiding tracks 38 and 40 in the form of elongated ellipses upon which the carriers 36 are adapted to travel through the various stations; an intermittent carrier feed 10 and lock mechanism 42, whereby the several carriers 36 are actuated step-by-step through their successive stations and are positively locked therein, a continuously operating chain conveyor 44 for actuating the several 15 carriers from the nailing station around the remaining portion of the tracks 38 and 40 to the nail-supplying station; a plurality of picker members 46 for removing the lowermost lifts L from their respective lift 20 magazines and transferring them laterally to the various assembling stations beneath the respective carriers; a nail-loading mechanism 48 (Fig. 22) for supplying nails N to the gripping means of the several carriers 25 36 when they respectively occupy the nail-loading station, a pasting and lift-impaling apparatus 50 for applying paste to the bottom surfaces of the various lifts after they have been transferred by the picker members 30 to the assembling stations and for impaling said lifts upon the nails that are gripped in the several carriers 36; a backing device 52 extending longitudinally of the machine and located above the various lift-assembling stations and against which the several carriers are raised during the impaling operation; a lift-supporting device 54 adapted to slide laterally for engaging the lower surfaces of the several lifts L after 35 40 they have been impaled upon the nails N of the respective carriers 36 for the purpose of preventing the withdrawal of the lifts when the paste-applying and lift-impaling apparatus 50 is removed; heel-block supplying conveyors 56 and 58, the former being adapted to supply previously formed heel-blocks B from a suitable source and the latter being adapted to transfer the blocks successively from the supply conveyor to an 45 50 other portion of the machine; a heel-block carriage 60 to which the heel-blocks B are transferred by the heel-block conveyor 58 and which actuates said blocks to the nailing station in which the blocks are positioned 55 in registry with the assembled lifts L upon the carrier which occupies the nailing station; a measuring and ejecting apparatus 62 for gaging the heights of the assembled leather lifts and the previously 60 formed heel-blocks and for ejecting any assembled pile of lifts or blocks that vary from predetermined dimensions; a nailing and pressure mechanism 64 for nailing the piles of assembled lifts on the respective 65 carriers to the previously formed heel-blocks positioned upon the block transferring carriage and for subjecting the assembled lifts and blocks to pressure; and a heel removal conveyor 66 for carrying away the completed heels that are built by the machine. 70

Referring to Figs. 1, 2, 3, 4, 5 and 6, the stationary frame 32, upon which the component elements of the machine are mounted, comprises side pedestal members 70 and 71, which are rigidly connected by means of 75 cross-members 72 and 73, and which support a bed plate or table 74. A plurality of upwardly projecting brackets or supporting plates 76, 78 and 79 are mounted upon the bed plate 74 near the respective 80 ends thereof.

The side pedestals 70 and 71 carry in suitable bearings 80 and 82 a main cam shaft 84, which is rotatably mounted therein and which carries a loosely mounted sleeve or hub 86 that is provided with a sprocket 88 that is fixed thereto. A main drive chain 90 cooperatively engages the teeth of the sprocket 88 and is driven in any well-known manner from a suitable source of power 90 (not shown). The chain 90 also cooperates with the teeth of an idler sprocket 92 (Figs. 5 and 6), which constitutes a part of an adjustable tension device. The sprocket 92 is rotatably mounted upon a shaft 94, having 95 bearings in a bifurcated arm 96 that is pivoted to the frame (Fig. 6). The arm 96 is provided with a portion 98 which is adapted to be engaged by the lower end of a rod 100 which loosely projects through the 100 respective ends of a yoke member 102 that is secured to the cross beam 72. A coil spring 104 surrounds the rod 100 between a collar 105 that is pinned to the rod 100 and a plate 107 that loosely surrounds the same, 105 said spring 104 serving to act upon the rod 100 to yieldingly hold the idler sprocket 92 in such a position as to maintain the desired tension upon the drive chain 90. Adjustable set screws 106 are threaded through the upper end of the yoke member 102 and cooperate with the plate 107 for adjusting the position of said plate and thus varying the strength of the spring 104, whereby the 110 tension of the drive chain 90 may be adjusted 115 to any desired amount.

One end of the sprocket sleeve 86, which is rotatably mounted upon the cam shaft 84, is provided with a gear 108 that meshes with a cooperating gear 110 that is fixed to 120 an auxiliary shaft 112, that is rotatably supported in suitable bearings in the side pedestal 70 and a dependent bracket 114 that is secured to the frame. The shaft 112 is also provided with a fixed gear 116 that meshes with a cooperating gear 118 that is fixed to the cam shaft 84 of the machine. The cam shaft 84 is provided with a plurality of cams 120, 121, 122, 123, 124, 125, 126, 127, 128 and 129, by means of which 130

the various component mechanisms of the machine are actuated in the proper timed co-operation, as will hereinafter be fully set forth.

- 5 The side pedestal 71 is provided with a lug 132 (Fig. 4) for supporting one end of a shaft 134, the other end of which is mounted in a lug 136 (Fig. 6) that is associated with the upper end of a supporting bracket 138
 10 which is secured to the cross-bracket 353. The various operating levers and bell-crank that cooperate with the several cams of the machine are mounted upon the shaft 134, as will hereinafter appear.
 15 Having described the general construction of the supporting frame of the machine, together with the mode of mounting certain of the most important shafts, consideration will be given to the various devices and
 20 mechanisms which go to make up the machine as a whole.

Referring more particularly to Figs. 1, 2, 3, 7, 9 and 10, the construction of the lift magazines or holders 34 will now be set forth. The lift magazines 34 are mounted in inclined positions in a row upon the bed-plate 74 at the front of the machine, and each comprises a breast plate 140 and a V-shaped heel member 142, which supports
 25 upon its respective faces a plurality of extended plates 144 that project upwardly and are adapted to engage the heel portions of a plurality of leather lifts L of graded sizes which are stacked in the magazine. The V-shaped heel member 142 is inclined to the horizontal and is provided with a base portion 146 which is connected therewith by a rib 148 and which is provided with spaced feet 150 that rest upon the bed-plate 74 and
 30 are secured thereto by means of bolts 152. The several feet 150 are provided with slots 154 through which the bolts 152 project, whereby the V-shaped heel member 142 and its associated plates 144 may be adjusted in
 35 position to accommodate the size of the lifts which are to be stacked in the magazine. The feet 150 of the adjacent heel members 142 are conveniently disposed the one above the other (Fig. 3) in order to bring the
 40 slots into registry whereby a single bolt 152 serves in common to fasten both heel members to the bed-plate 74.

Each of the breast plates 140 is disposed substantially parallel to the inclined heel
 45 members 142 and is secured at its upper end to a longitudinal rod 156 by means of a lug 158 that is associated therewith. The supporting rod 156 is mounted at its respective ends upon upwardly projecting arms
 50 160 and 162 (Fig. 3) that constitute integral parts of the respective brackets 76 and 78. The lower end of the breast plate 140 is provided with a boss 164 that is secured to a cross-bar 166 that extends longitudinally
 55 of the machine and is supported at its respec-

tive ends by means of arms 168 and 170 (Figs. 1 and 2), which are fixed to a shaft 172 that is suitably mounted on the upwardly projecting brackets 76 and 78.

Between the lugs 158 and 164, the breast 70 plate 140 is provided with spaced lugs 174 and 176 (Figs. 6 and 9), in which a rod 178 is fixedly mounted. The rod 178 is threaded throughout its upper portion and is provided with a knurled thumb screw 180 75 that forms a part of a spool having spaced flanges 182. The spool is threaded to cooperate with the threads on the rod 178 whereby the said spool is caused to traverse the rod longitudinally when the thumb screw 80 180 is turned. A block or plate 184 is loosely mounted on the rod 178 and is provided with tapering slots 186 that are convergent downwardly. An L-shaped plate 188 is screwed to a boss 190 on the block 184 85 and its short arm 189 is provided with a semi-circular recess which forms spaced outer arms which project loosely into the groove between the flanges 182 of the travelling spool in such manner that the 90 longitudinal movements of the spool are transmitted to the slotted block 184.

The tapering slots 186 are adapted to receive the ends of pins 191 that are respectively carried by the upper ends of levers 192, which are oppositely disposed and pivotally mounted to the breast plate 140 upon pins 194. The lower ends 196 of the levers 192 are provided with angularly disposed plates 198, which serve as guides to 100 cooperatively engage sides of the leather lifts L that are stacked in the lower end of the magazine. By suitably adjusting the spacing of the guide plates 198 by means of the thumb screws 180, the several magazines 105 may be adapted to guide and definitely position any size of lifts.

The lower end of the breast plate 140 is provided with a centrally located longitudinal recess 200 (Figs. 7 and 8), in which is 110 located a loosely mounted finger or gate 202. The upper end of the gate 202 carries a pin 204 that is adapted to loosely rest in recesses 206 that are formed in the sides of a channel or U-shaped member 208 that projects outwardly from the breast plate 140, and is attached thereto over the central recess 200 115 therein (Fig. 9). The lower end of the gate 202 is provided with a pin 210 that is movably positioned in elongated slots 212 in the respective sides of the channel member 208. The lower end of the gate 202 is further provided with a laterally extending plate 214 that has a beveled lower edge. The gate 202 is normally maintained in the position 120 shown in Fig. 7 by means of a spring 216 which surrounds a rod 218 that has a pivotal knife-edge bearing 219 upon the gate 202 and projects through an opening in the bridging portion of the channel member 208. 130

One end of the spring 216 rests against the gate 202 and the other end engages the above-mentioned bridging portion of the channel member 208.

5 The purpose of the gate 202 is to prevent the lateral withdrawal of more than the lowermost lift L in the stack contained within the magazine. As the lowermost lift is withdrawn to the right (Fig. 7) by a picker member 46, in a manner to be set forth, the gate 202, by reason of its peculiar mode of mounting, is permitted to be raised slightly to allow a single lift to be removed by the picker member 46 during its sliding transferring movement toward the carriers 36. During the return movement of the picker member, engagement is effected with the lower end of the gate 202, which is, in consequence, raised and slightly rotated outwardly upon the pin 210 to permit the return passage of the picker member.

Reference may now be had particularly to Figs. 8, 14, 15 and 17, which illustrate the details of construction of one of the independent movable carriers or cars 36, upon which leather lifts are progressively assembled as the carriers are actuated step-by-step through their successive assembling stations, as will hereinafter be fully described. In structure, the several carriers 36 are alike, and each comprises a substantially rectangular plate 220 which constitutes the body of the carrier and which is provided with a relatively large rectangular central opening extending entirely through it and having longitudinal shoulders 222. A pair of complementary angle members 224 are inserted within the central recess above referred to, and these angle members 224 are provided on three sides with upper lateral flanges 226, which rest upon the respective shoulders 222 and are secured thereto by screws 248, or other suitable means. The complementary angle members 224 are in duplicate and are so positioned within the recess that their abutting inner faces meet on a central line. Each of the angle members 224 is provided with laterally extending slots or recesses 228 that register the one with the other to provide a plurality of elongated lateral slots that are equally spaced apart. Loosely disposed within each of these elongated slots 228 are a pair of complementary blocks or jaw members 230, which have upper longitudinal flanges 232 that rest and slide upon the upper edges of the angle members 224. The inner faces of each of the complementary blocks or jaw members 230 are provided with small semi-cylindrical recesses, which, taken together, provide an opening 233 to receive an impaling member comprising a nail N or the like.

The body portion 220 of each carrier 36 is further provided with laterally disposed parallel recesses 234, which also extend

through the angle members 224, and are adapted to receive a plurality of coil springs 236 that are disposed in pairs, one on each side of the complementary jaw members 230. These springs 236 are retained in position within the recesses 234 of the carrier by means of screw members 238 that are threaded into the outer ends of the several lateral recesses 234. The springs 236 bear against the screw members 238 at one end and against the outer faces of the complementary jaw members 230 at the other, whereby said jaw members are maintained in engagement and gripping relation to the nails N which may be placed in the openings 233 between them.

In order to centralize the jaw members 230 and nails gripped thereby, one of each set of complementary jaw members 230 is provided with a corner recess 240, in which a small pin 242 is located, said pin being secured to a bottom plate 244 that covers substantially the entire bottom surface of the carrier and which is attached thereto in a suitable manner.

One end of the carrier 36 is provided with a pair of outwardly projecting portions 250 which are adapted for traveling engagement with the track 38 and are spaced apart to form a slot 251. The other end of the carrier is provided with an oppositely projecting member 252, which is disposed above the bottom surface of the carrier and which is provided with a pair of pivotally mounted rolls 254 that are located directly beneath the projecting member 252 and which are adapted to cooperatively engage the track 40 for the purpose of positioning the carrier with respect thereto. The projecting member 252 has integral upwardly extending and rounded corner bosses 256 which are respectively adapted to engage similar bosses on the adjacent carriers 36 and which determine the spacing between them. Moreover, these rounded corner bosses 256 also serve to actuate the preceding carrier through certain portions of the track, as will hereinafter appear. Substantially midway between the rounded spacing bosses 256, the projecting member 252 is provided with an upwardly extending boss 258 that has an outward extension 259 by means of which the chain conveyor 44 actuates the carrier through certain portions of the tracks, as will later appear. A pivotally mounted roll 260 is positioned above the boss 258 and is adapted to be engaged by part of the carrier feed and lock mechanism 42, whereby the carriers are actuated step-by-step through certain of their stations.

As already stated, the several carriers 36 are adapted to be guided by and travel upon the tracks 38 and 40 (Figs. 1, 2, 8 and 12). The several tracks 38 and 40 are in the

form of elongated ellipses and are positioned the one within the other and are mounted upon spacing blocks 261 and secured to the bed-plate 74 in a suitable manner. The outer track 38 comprises straight sections or bars 262 and semi-circular end portions 264 which abut against the respective ends of the straight sections 262 and form a continuation thereof. The inner track 40 comprises an elongated plate of grooved cross-section, having inner and outer flanges 270 and 268 that are spaced apart to form a slot or groove that is concentric with the outer track 38. The several carriers are disposed between the outer and inner tracks 38 and 40 and are adapted to travel therein. The rolls 254 that are located at one end of the carriers are disposed within the slot or groove of the inner track 40, while the outer ends of the extended portions 250 of the carriers are adapted to have a sliding engagement with the inner surface of the outer track 38. Thus, the carriers are definitely positioned and guided by the tracks 38 and 40.

There are three more carriers 36 than there are lift magazines 34 and picker members 46, so that, in addition to having carriers occupy the various assembling stations 30 in which lifts L are progressively assembled thereon and which are equal in number to the lift magazines and picker members, carriers also occupy a nail-loading station shown at the left in Fig. 12, a nailing station shown at the extreme right in Fig. 12, and a measuring station illustrated in Fig. 12 intermediate the aforesaid stations. The several carriers 36 occupying the nail-loading station and the successive lift assembling stations, are each positively engaged by parts of the carrier feed mechanism 42, which will now be described, and are independently and concurrently actuated thereby. The carrier in the measuring station, 45 however, is not independently and positively actuated, but is advanced into the nailing station at the same time that the other carriers are positively actuated by the carrier feed mechanism 42 by reason of the 50 cooperative engagement of the rounded corner spacing members 256, as will be understood.

The carrier feed and lock mechanism 42, through the agency of which the carriers in 55 the nail-loading station and the successive assembling stations are intermittently and independently advanced and subsequently positively locked is substantially like that disclosed in my prior Letters Patent of the 60 United States No. 1,181,091, April 25, 1916, and comprises (Figs. 1, 2, 6 and 8) a longitudinally movable rock-shaft 274 that is supported in suitable bearings 276 and 278 that respectively form parts of the upwardly projecting brackets 76 and 78. This

shaft 274 extends between the brackets 76 and 78 and, in fact, projects beyond the bracket 76, and is located directly above the forward straight section of the track 40. The shaft 274 carries a sleeve 280 that is 70 fixed thereto and extends only a portion of the length of the shaft 274 between the bearings 276 and 278. The upper portion of the sleeve 280 is provided with a longitudinal radial flange 282, while the lower portion thereof is provided with an oppositely projecting flange 283 having a plurality of pairs of spaced lugs 284 that are adapted to be brought into engagement with the several rolls 260 of the carriers 36 that occupy the various assembling stations.

A semi-cylindrical sleeve 286 loosely surrounds the forward half of the sleeve 280 and is provided with end bearing members 288 and 290, by means of which the sleeve is 85 rotatably mounted upon the shaft 274. The upper and lower radial faces of the semi-cylindrical sleeve 286 rest against the radial flanges 282 and 283 of the sleeve 280, and the lower portion of the sleeve member 286 90 is provided with a plurality of pairs of spaced lugs or fingers 292, which are adapted to be brought into engagement with the rolls 260 of the several carriers 36.

Since the sleeve 280 is fixed to the shaft 95 274, any longitudinal or rotative movements that are given thereto are transmitted to said sleeve. The semi-cylindrical sleeve 286, being loosely associated with the sleeve 280 and extending the full length of the shaft 100 274 between the brackets 76 and 78, is not permitted to move longitudinally, however, but will have rotative movements in accordance with the rotative movements of the sleeve 280.

The shaft 274 is longitudinally reciprocated in the following manner: The extended end of said shaft (Figs. 1 and 3) is provided with a fixed spool having spaced flanges 296, between which a split ring 298 110 is located and loosely positioned. Opposite points of the split ring 298 are pinned to spaced links 300 that are pivotally connected to the upper end of an arm 302 of a bell-crank which is pivotally mounted upon a 115 shaft 304 and which is provided with another arm 306. The outer end of the arm 306 has a universal connection 308 (Figs. 5 and 6) to the upper end of a rod 310, the lower end of which has a universal connection 312 to one end of an arm 314 which is pivotally mounted upon the shaft 134, the arm 314 being provided at substantially its mid-point with a roll 316, which travels in a cam path in the cam 121, which is secured 125 to the main cam shaft 84. The cam 121 is constructed and positioned upon the cam shaft 84 to effect, through the intermediate connections just described, the desired reciprocal movements of the shaft 274 130

whereby the sleeve 280 and its associated fingers 284 are similarly actuated.

The rotative movements of the shaft 274 and the associated sleeve 280 and 286 are effected through the agency of the following mechanism: The left-hand bearing member 288 of the semi-cylindrical sleeve 286 is provided with an upwardly projecting arm 320 (Figs. 1 and 6), which is pivotally connected by means of links 322 to the upper end of an arm 324 of a bell-crank that is rotatably mounted upon a shaft 326. The shaft 326 is supported in suitable bearings by the brackets 76 and 78 and by an intermediate upwardly and inwardly extending bracket 330 that is suitably secured to the back portion of the bed-plate 74. The other arm 332 of the bell-crank, above referred to, has a pivotal connection with the upper end of a rod 334, the lower end of which is pivotally connected to one end of an arm 336 that is rotatably mounted upon the shaft 134 and is provided with a roll 340 which travels in a cam path upon the cam 120 that is fixed to the cam shaft 84. The cam 120 is designed and angularly positioned upon the shaft 84 so as to effect periodic rotative movements of the sleeve 286. These movements are in the proper timed-cooperation with the reciprocating movements of the shaft 274 and are, of course, transmitted to the sleeve 280 by reason of the peculiar mechanical association of these two sleeves.

When the sleeves 280 and 286 occupy the positions shown in Fig. 8, the fingers 292 of the semi-cylindrical sleeve 286 engage the opposite sides of the several rolls 260 of the respective carriers 36, and thereby lock said carriers positively in their respective assembling stations. In order to effect an advance of the carriers into their next succeeding stations, the cam 120, through the mechanical connections just described, rotates the associated sleeves 280 and 286 in a clockwise direction, whereby the fingers 292 become disengaged from the rolls 260 and the fingers 284 are brought into engagement therewith. Subsequent to this operation, the cam 121 actuates its mechanical connections in such a manner as to cause the shaft 274 and the sleeve 280, which is fixed thereto, to be moved longitudinally to the right (Figs. 1 and 2), whereby the several carriers 36 are positively and independently advanced a step into the next succeeding stations by reason of the engagement of the fingers 284 with the respective rolls 260 thereof. After the forward actuation of the carriers 36 in the manner described, the cam 120 returns the associated sleeves 280 and 286 in the opposite direction and into the positions illustrated in Fig. 8. Thus, the fingers 284 of the longitudinally movable sleeve 280 become disengaged from the rolls 260,

while the locking fingers 292 of the sleeve 286 are brought into engagement therewith, whereby the several carriers 36 are positively locked in the assembling stations which they respectively occupy. This cycle of operation is periodically repeated in the manner set forth, to the end that the carriers 36 are concurrently advanced step-by-step through their successive assembling stations, in which lifts L are progressively superposed in a manner to be hereinafter set forth. Obviously, at each step of advancement of the carriers 36, the carrier which occupies the measuring position (Fig. 12) is pushed into the nailing position, whereby all of the carriers are intermittently actuated through all of the various stations. In order to prevent the carriers from overshooting the nailing station, a yielding stop 341 (Figs. 12 and 23) comprising a plurality of leaf springs is provided for engaging the several carriers as they are moved into the nailing station.

In order to rapidly return each carrier 36 to the nail-loading station from the nailing station, after it has been vacated by the completed heel, as will be hereinafter described, the continuously operated relatively rapidly moving chain conveyor 44 is employed. This chain conveyor 44, which may be of any well-known type, is located within the track 40 (Figs. 1 and 2) and is carried upon a plurality of sprockets 342 and 344, which are located within and concentric with the respective ends of the track 40. The sprocket 344 is rotatably mounted upon a stud 346 that is secured to a boss 347 on the bed-plate 74, while the sprocket 342 is carried by a hub member 348 (Fig. 8), which is fixed to the upper end of a vertical driving shaft 350 (Figs. 3 and 6) that extends through bosses 349 upon the bed-plate 74. The lower end of the shaft 350 is suitably journaled in a bearing 351 upon the bracket 353 (Fig. 3) and is provided with a mitre gear 352 which meshes with a cooperating mitre gear 354 that is fixedly mounted upon the auxiliary shaft 112, the latter being continuously driven by the main drive chain 90 through the connections which have already been described. It is evident, therefore, that the chain conveyor 44 is operated continuously whenever power is applied to the machine.

In order to independently and individually actuate the several carriers 36 from the nailing station around the track to the nail-loading station, the chain 44 is provided with a triangular pusher member 356 (Fig. 12) that is pivotally mounted upon an extended pin 358 which constitutes a part of the chain. The pusher member 356 is also provided with a pivoted roll 360 which is adapted to engage an upwardly extending curved cam member 362 which extends con-

centrically within the curved portions of the track 40 and across the rear straight section thereof. The cam member 362 is mounted upon a plate 363 that is supported 5 above the bed-plate 74 upon the bosses 347 and 349. The roll 360 is adapted to project into a groove formed between the curved cam member 362 just referred to and the inner flange 270 of the track 40, and 10 while travelling in this position the pusher member 356 is maintained in a lateral position to engage the lug 259 upon the carriers. This engagement is effected with the carrier in the nailing station, whereby said carrier 15 is rapidly returned to the nail-loading station, where the roll 360 of the pusher member disengages the curved cam member 362 which results in the disengagement of the pusher member 356 with the lug 259 of the 20 carrier which has just been actuated. The forward section of the chain 44 is caused to travel behind an adjustable guide and tension member 364 that is secured to the plate 363 and this guide member 364 is positioned 25 near the center line of said plate so as to carry the forward section of the chain in such manner as to insure the disengagement of the pusher member 356 with all of the carriers throughout their several stations. 30 It will be understood, therefore, that the several carriers 36 are actuated step-by-step through the several stations and are picked up at the nailing station after the completed heel has been discharged and 35 rapidly carried around the track to the nail-loading station.

For the purpose of spacing the chain vertically from the plate 363, said chain is provided at intervals with downwardly projecting rolls or members 366 (Fig. 8), the lower 40 ends of which may travel upon said plate.

The transferal of lifts from the respective magazines 34 to the successive assembling stations which are occupied by the carriers 36 is effected by the picker members 46. For an illustration thereof, reference 45 may be had to Figs. 1, 3, 7, 11, 12, and 13. Referring particularly to Fig. 12, the bed-plate 74 is provided with a longitudinal 50 opening 370 that extends throughout the several assembling stations below the carriers which travel in the tracks 38 and 40. The bed-plate 74 is further provided with a plurality of parallel transverse slots 372 55 which open into the opening 370 and which are located beneath and central with the several lift magazines 34. Guide members 374 having slots 376 therein are fastened to the under side of the bed-plate 74 and are 60 located on either side of the respective slots 372, and these guide members together with the slotted bed-plate 74 serve to support and guide the respective picker members 46.

The several picker members 46 are of like 65 construction and each comprises (Fig. 7) a

lower plate 378 that is adapted to slide in the grooves of the guide members 374 and which is loosely associated with an upper plate 380 that is disposed above the bed-plate 74 and is provided with a tongue 382 70 that projects downwardly in the slot 372. The inner end of the lower plate 378 is provided with a longitudinal slot to receive a link 384, one end of which is pivoted to the lower plate by a pin 379 and the other end is 75 pinned to the tongue 382 of the upper plate 380. The outer end 388 of the link 384 constitutes a tail piece for engagement with the lower plate 378 to definitely position the upper plate 380 with respect thereto. 80 Pivotally mounted upon the pin 379 and on opposite sides of the link 384 are bifurcated lugs 390 of an arm 392 that projects outwardly and upwardly through the slot 372 and just ahead of the inner end of the upper 85 plate 380.

The free end of the pivotally mounted arm 392 is provided with lateral arms 394 that normally rest upon the sides of the slot 372. A plurality of fingers 396 in the form 90 of bell-crank are pivotally secured to the opposite ends of the lateral arms 394 by means of screws 398, which screws also serve to secure a top plate 400 in position above the fingers 396. A U-shaped spring 399 cooperates with the fingers 396 and tends to maintain them in gripping relation to the lift L that may be disposed between them. Normally, the outer edge of the plate 400 is adapted to rest in a slight recess in the 100 inner end of the upper plate member 380, whereby the downward movement of the pivotally mounted arm 392 is limited. The bell-crank, of which the fingers 396 form parts, are each provided with short arms 402 105 that are provided with inter-meshing teeth 404, whereby said fingers 396 are concurrently actuated through like distances. The free ends of the fingers 396 are provided with inwardly projecting thin fins or knife 110 edges 406 (Figs. 11 and 12), which are adapted to slide beneath the lowermost lift L in the magazine and to support the same after its removal therefrom.

The actuation of the gripping fingers 396 115 is also effected by means of a small connecting rod 408, one end of which is associated with one of the short arms 402 of one of the bell-crank, the other end of which is pivotally connected to the end of an arm 120 410 that constitutes a part of a bell-crank which is pivoted on a pin 412 carried by the upper plate 380 and having another arm 414 associated therewith. The end of the arm 414 is provided with a pin 416 which 125 projects downwardly into engagement with a surface of a cam plate 418 that is adjustably mounted upon the bed-plate 74. The pin 416 is normally maintained in engagement with the cam plate 418 by means 130

- of the trunnion, the annular member 625 is normally maintained in its inner or set position, in which the pins 626 of the clutch project into the openings 624 of the gear 604 and effect a driving connection. In Figs. 19 and 20, the clutch is illustrated as disconnected, and is restrained in such position by means of a latch 646 that is pivotally mounted at its lower end upon a pin 648 and is provided with a shoulder 650 that engages the upper side of the arm 638. The latch 646 is maintained in engagement by means of a spring 652 that has its respective ends attached to the latch 646 and to a pin 654 that is secured to the bracket 612. In order to cause the clutch to establish a driving connection with the gear 604, the latch 646 is withdrawn from the arm 638, whereby the spring 642 is permitted to actuate the pins 626 into the openings 624 of the gear 604. In order to limit the movement of the pins 626, a set-screw 658 is provided in the supporting bracket 612 for engagement with the yoke portion 632 of the trunnion. Power is applied to the sprocket 618 that is fixed to the shaft 616 by means of a chain 660 (Figs. 3, 20 and 21) that cooperates with said sprocket and with a sprocket 662, that is fixed to an auxiliary shaft 664 that is mounted upon a bracket 665 that is bolted to cross-beams 72 and 73 and is provided with a mitre gear 666 (Fig. 5) that meshes with a cooperating mitre gear 668 that is secured to the main cam shaft 84. An adjustable idler sprocket 670 (Fig. 3) is provided to cooperate with the chain 660 for the purpose of maintaining it under any desired tension. Assuming the clutch, hereinbefore described, to establish a driving connection with the gears 604 and 606 whereby power is applied thereto, the pasting and impaling plunger 514 is periodically reciprocated in a vertical direction and into engagement with the lower surfaces of the several lifts L that are supported in the gripping fingers 396 and 430 of the picker members 46. Inasmuch as the plunger 514 is immersed in paste at each reciprocation thereof, it is evident that paste is applied to the lower surfaces of the lifts at each engagement thereof. The excess paste is removed from the plunger 514 during each upward movement thereof, by means of the scraper rod 583, as already explained. Subsequent to the initial engagement of the pasting plunger 514 with the lifts L, said lifts, together with the inner pivotally mounted portion of the picker arms 46, are raised, during which movement the lifts are impaled upon the downwardly projecting nails N that are gripped in the several carriers 36. Moreover, the lifts L are forced upwardly upon the nails N until they come into engagement with the lower face of the carriers, after which the carriers are also elevated in position for the purpose of progressively driving the nails through the lifts, as will be set forth. It will be readily understood that, at each upward movement of the plunger 514, the lifts L supported in the respective picker members 46 are concurrently coated with paste and impaled upon the nails N in the respective carriers which are located in the assembling stations. During the intervals between each impaling operation, the carriers are advanced a step into the next succeeding station and new lifts are transferred from the magazines 34 by the picker members 46, so that upon the subsequent upward movement of the plunger 514, additional lifts are impaled upon the nails of the carriers, whereby heel piles are progressively built up or assembled. Acting in conjunction with the plunger 514 during the impaling operation, the backing device 52 is employed for yieldingly resisting the upward movement of the plunger 514 and the carriers 36 and for providing a rigid backing against which the heads of the nails N rest while the lifts L are impaled thereon. This backing device 52 comprises (Figs. 1, 2, 3, and 8) a stationary backing member 674, of substantially T-shaped section, that extends longitudinally of the machine and embodies at its left end a U-shaped member 676 that projects upwardly and extends over the nail loading mechanism 48. The depending end 680 of the U-shaped portion of the backing member 674 is adjustably secured to the upright bracket 76, while the other end thereof is adjustably fastened to the upright bracket 78. By reason of the adjustable mounting of the backing member 674, the machine may be readily adapted for different lengths of nails N. The horizontal part of the head portion 682 of the backing member 674 is disposed directly above the several carriers 36, occupying the successive assembling stations, and is vertically spaced therefrom. The web portion 684 of the backing member 674 is provided with a plurality of longitudinally spaced sets of transversely extending arms 686 and 688, and these sets of arms are respectively located above the center-line of the carriers 36 in the successive assembling stations. Each of the sets of arms 686 and 688 is provided with vertically movable rods 690 that project through openings in the ends of said arms, and which are surrounded by coil springs 692. The coil springs, just referred to, rest upon collars 694 that are secured to the rods 690, and the upper ends of said springs act against the upper arms 686, whereby said rods 690 are maintained in their lowermost positions, as indicated in Fig. 7. The upper ends of the rods 690 are provided with stop collars 696 to limit the

downward movement thereof and the lower ends carry plates 698 that have a sliding engagement with the edges of the head portion 682 of the backing member 674. These 5 plates 698 are normally positioned slightly above the carriers 36 and are adapted to engage the upper surfaces thereof when the reciprocating plunger 514 is in the act of impaling lifts upon the nails N gripped thereby. 10 As already explained, this operation is accompanied by an elevation of the several carriers 36, which movement is resisted and cushioned upon the plates 698 by reason of the action of the coil springs 692. As the 15 carriers 36 are raised by the plunger 514 during the impaling operation, the heads of the nails N are brought into engagement with the lower surface of the head portion 682 of the backing member 674, which serves as a 20 backing for the nails N to assist in impaling the lifts thereon.

As lifts are successively impaled on the nails N of any particular carrier as it is advanced step-by-step through the various 25 assembling stations, the carrier, by reason of the additional lifts, is progressively raised an increased amount during each impaling operation, and hence the nails N are correspondingly driven through the impaled lifts 30 by successive increments until, in the last assembling station, the carriers are raised to their extreme height and the heads of the nails are brought into substantially the plane of the upper surface of the carriers, as illustrated in Fig. 8.

For the purpose of preventing the withdrawal of lifts from the nails N, upon which they have been impaled, by the downward movement of the reciprocating pasting and impaling plunger 514, the lift-supporting device 54 (Figs. 6, 8 and 12) is employed. This device comprises a plurality of transversely slidable frames 700 and 702 that rest upon the back portion of the bed-plate 74 and are provided with a plurality of sets of spaced fingers 704 that project laterally in a forward direction therefrom. The sliding frames 700 and 702 are spaced apart and are held down by end guide members 706 and 708 and a middle guide member 710 while the said frames 700 and 702 are guided laterally by means of keys 712, which are fixed to the bed-plate 74 and project into transverse slots in the under sides of said frames. The several lift-supporting fingers 704 are so located that their upper surfaces are substantially flush with the upper surface of the reciprocating plunger 514 when in its extreme uppermost position, and hence, 55 said fingers may be projected forwardly immediately beneath the lowermost lift L upon the several carriers 36, so as to temporarily support the lifts at the moment that the plunger 514 is withdrawn in a downward direction. Thus, it is impossible for the lower-

most lifts to adhere to the plunger 514 and be pulled away from the nails N during the downward movement of the plunger.

In order to accommodate the lift-supporting fingers 704, the stop bar 476 is provided with a plurality of openings 714 (Fig. 18), through which the fingers 704 may be projected. Moreover, the slots 576, which have hereinbefore been described as provided in the upper edges of the plunger 514, are also 75 positioned to receive the lift-supporting fingers 704 when the plunger 514 is in its uppermost position and said fingers are projected beneath the lifts upon the carriers.

The sliding frames 700 and 702 are connected to a plurality of lever arms 716 and 718 (Figs. 1, 2, 8 and 12) that are respectively associated with the frames 700 and 702 by means of pivotally connected links 720 and 722. The lever arms 716 and 718 are clamped to the horizontal shaft 724, which extends longitudinally of the machine and is supported in suitable bearings upon the upright brackets 76 and 78 and in the overhanging intermediate bracket 330. The shaft 724 is also provided with a fixed upwardly projecting arm 726 (Figs. 2 and 6) that is pivotally connected to an arm 728 by means of links 730. The arm 728 constitutes a part of a bell-crank that is pivotally mounted upon the shaft 326, and its other arm 732 has its outer end pivotally associated with the upper end of a rod 734. The rod 734 is surrounded by a coil spring 733, the ends of which engage the bed-plate 74 and a fixed collar 735. Said spring serves to yieldingly actuate the sliding frames 700 and 702 inwardly to position the lift-supporting fingers beneath the lowermost lifts on the carriers 36. The lower end of the rod 734 is pivotally connected to the outer end of a lever arm 736 which is pivotally mounted upon the shaft 134. The lever arm 736 carries a roll 738 which engages the periphery of the cam 124 that is fixed to the main cam shaft 84. The configuration of the cam 124 is such as to periodically actuate the sliding frames 700 and 702 back into their inoperative positions against the action of the spring 733 and through the agency of the intermediate connections, just described. Moreover, the angular position of the cam 124 with respect to the other cams upon the shaft 84 is such as to permit the temporary forward actuation of the frames 700 and 702 and their associated lift-supporting fingers 704 at the time that the reciprocating plunger 514 initiates its downward movement and to positively return said frames after the fingers 704 have served their functions. Thus, the lift-supporting fingers 704 are brought into operation merely for a short period to prevent the withdrawal of lifts L from the nails N in the several carriers as the plunger 514 moves 130

jaw members 230 of the carriers which successively occupy the nail-loading station.

This driving operation is effected by means of the reciprocable nailing block 482 which is pivotally connected to the outer end of an arm 500 by means of a lost-motion link 502. The arm 500 is pivotally mounted upon the shaft 326 and its hub portion is provided with another integral arm 504, the outer end of which has a pivotal connection to the upper end of a rod 506. The lower end of the rod 506 is pivotally connected to the outer end of an arm 508 (Fig. 6) that carries a roll 510 and is pivotally mounted upon the shaft 134. The roll 510 cooperates with a cam path on the cam 122 that is fixed to the cam shaft 84. The cam 122 is so constructed and angularly positioned upon the shaft 84 with respect to the other cams thereon as to periodically actuate the nailing block 482 downwardly and at such times as the nail-loading station is occupied by one of the carriers 36.

As the nailing block 482 moves downwardly, during its working stroke, the pins 488 are forced into the openings 492 and against the heads of the nails N that have been loaded therein by the nail-feeding device (not shown), whence said nails are driven through the openings 492 and into the openings formed between the complementary gripping jaw members 230 of the carrier 36, which occupies the nail-loading station. Having thus driven or loaded the nails N into the gripping devices of the carrier, the cam 122 effects an upward movement of the nailing block 482 to its normal position, where it remains until another carrier is brought into the nail-loading station by the chain conveyor 44, in the manner already described.

The manner in which the nails N are loaded into the several carriers having been set forth, reference may be had to Figs. 3, 6, 8, 18, 19, 20, and 21, in connection with which the construction and operation of the pasting and lift-impaling apparatus 50 will be described.

Assuming that the several picker members 46 have transferred single lifts L from the respective magazines 34 to the assembling stations, in which they are supported by the gripping fingers 396 and 430 beneath the respective carriers which have already been loaded with nails N, said lifts are coated with paste and impaled upon said nails by means of a vertically reciprocating plunger 514. This plunger 514 extends longitudinally of the machine and beneath the carriers 36 in the several assembling stations, and is adapted to be immersed in a suitable liquid paste contained within an open tank 516. The tank 516 is rectangular in form and is removably sup-

ported in position beneath the bed-plate 74 upon a plurality of sets of rolls 518 (Figs. 3 and 6) that are carried at the upper end of a pair of supporting members 520, each of which comprises a hub portion 522 and 70 a pair of integral parallel arms 524 that are joined by a rib 526 and to the upper ends of which the rolls 518 are pivotally mounted. The supporting members 520 are respectively fixed to shafts 528 and 530 that 75 are supported by cross beams 532 and 534 that extend longitudinally of the machine and beneath the tank 516. The rib portions 526 of the several supporting members 520 are pivotally connected by a rod 536 80 and the supporting member 520 that is mounted upon the shaft 528 is provided with a depending arm 538. The end of this arm 538 has a pivotal connection to one end of a rod 540 (Fig. 3) and the other end 85 thereof is pivotally connected to the lower end of a link 542 that depends from a stud 544 that is carried by brackets 546 which are secured to the side pedestal 70. Furthermore, this end of the rod 540 is also 90 pivotally connected to an intermediate point of a bell-crank having one arm 548, which constitutes a handle, and another arm 550 that forms a part of a toggle joint which is completed by an arm 552 that is pivotally connected to the end of the arm 550 and which is pivotally mounted upon a stud 554 carried by the cross beam 73.

When the handle 548 is depressed to its lowermost position, as shown in Fig. 3, the arms 550 and 552, comprising the toggle joint, are set and suitably maintained in a position just behind their dead-center, whereby the rod 540 is held in its extreme left-hand position to hold the several supporting members 520 vertically and thus support and force the tank 516 upwardly in its operative position. In the raised position of the tank 516, the upper edges thereof are engaged and positioned by a plurality of guide members 556 (Fig. 6) in the form of angle irons which are secured to the bottom of the bed-plate 74. In order to remove the tank 516 and the apparatus associated therewith and to be hereinafter described, for the purpose of cleaning, it is only necessary to raise the handle 548 to break the toggle comprising the arms 550 and 552, whereby the supporting members 520 are rotated downwardly in a counter-clockwise 105 direction to lower the tank 516, after which it may conveniently be withdrawn.

The tank 516 is provided at one end with an over-flow outlet 558, which determines the level of the paste contained therein. The 110 respective ends of the tank are provided with end plates 560 and 562, having corresponding slightly curved and inclined slots 564, for a purpose which will later be made to appear. The plunger 514 is relatively 115 120 125 130 135

long and its respective ends are adapted to have a travelling engagement with the plates 560 and 562, between which the plunger 514 is permitted to reciprocate in a vertical direction.

- The plunger 514 comprises a pair of parallel side members 566 that are spaced apart and rigidly joined by integral end ribs 568 and 570 and by an intermediate rib 572.
- 10 The upper edges of the parallel side members 566 are furthermore connected by means of cross-members 574, which are laterally spaced to permit the ready dripping of paste when the plunger 514 has been 15 raised above the level of the paste within the tank 516. Certain of the cross-members 574 are provided with rows of openings in which small wooden disks 575 (Figs. 8 and 21) are set to engage the ends of the nails N 20 upon which the lifts L are impaled. Moreover, the side members 566 are also provided with registering slots 576 (Fig. 18), for a purpose to be hereinafter set forth. The plunger 514 is loosely mounted upon a 25 plurality of crank-pins 578 and 579, which are adapted to move longitudinally with respect to the plunger through suitable open-ended slots 580 that are provided between the lower edges of the side members 566 30 and downwardly and longitudinally projecting arms 582 that are integral therewith. The extremities of the last mentioned arms 582 are rigidly connected by means of ribs 584. Slidably mounted in the curved and 35 inclined cam slots 564 in the end plates 560 and 562 is a scraper rod 583 that extends longitudinally of the tank 516 and is engaged and forced across the upper surface of the plunger 514 during its upward movement whereby excess paste is scraped therefrom. The scraper rod 583 is normally biased to the lower ends of the cam slots 564 by means of pivotally mounted fingers 585 that are acted upon by coil springs 587.
- 40 The rear ends of the crank-pins 578 and 579 are carried by the free ends of crank-arms 586, which are fixed to studs 590 that are rotatably mounted in aperture bosses 592 that constitute integral parts of the tank 50 516. The front ends of the crank-pins 578 and 579 are carried in the free ends of crank-arms 594, which are inserted in grooves through the center of disks 596 that are fixed to studs 598. The crank-arms 594 55 are bolted in position to the disk 596 by bolts 600, and the studs 598 are pivotally mounted in apertured bosses 602 that are integral with the tank 516. The studs 598 project beyond the tank 516 and are respectively provided with gears 604 (Figs. 3 and 21) that are fixed thereto. Intermediate the gears 604 and meshing therewith, is an idler gear 606 which is rotatably mounted upon a stud 608 that is carried by a multi-arm 60 bracket member 610 that is bolted to the

outside of the tank 516. The crank-pins 578 and 579, therefore, are mechanically interconnected by the gearing just described, so that they are moved in unison upon their crank arms whenever the above mentioned 70 gearing is actuated. Obviously, as the crank-pins 578 and 579 are rotated by means of the crank arms 586 and 594, said pins have a sliding movement in the slots 580 of the plunger 514, and during their rotation, 75 reciprocate the plunger 514 up and down, as will be understood.

The gears 604 and 608 are driven through a clutch which will now be described. Referring to Figs. 6, 19, 20 and 21, a bracket 612 is supported upon the cross-beams 73 and 532, and said bracket projects upwardly to form a bearing 614 in which a shaft 616 is rotatably mounted. The outer end of the shaft 616 is provided with a fixed sprocket 618 while the other end thereof is provided with a fixed clutch member 620, comprising oppositely projecting arms, the ends of which are provided with openings 622 that are adapted to register with similar openings 624 through the gear 604. The shaft 616 abuts against the end of the stud 598 and is in alignment therewith. An annular member 625 surrounds the bearing 614 and is spaced therefrom, and, moreover, is provided with fixed laterally projecting pins 626. The pins 626 are adapted to normally project into openings 622 in the clutch member 620 and may be moved longitudinally to project into the openings 624 of the gear 604. Under these conditions, it is evident that the gear 604 and the clutch member 620, which is fixed to the shaft 616, are rigidly connected, whereby a driving connection is effected. When the annular member 625 and 105 its associated pins 626 are moved to the left (Fig. 19), however, the pins 626 are withdrawn from the openings 624 of the gear 604 and the driving connection is thus disengaged.

In order to actuate the annular member 625 in and out to cause the clutch to be engaged and disengaged, a plurality of grooved members 628 are employed. These members 628 cooperate with the periphery of the annular member 625 and are pivotally mounted upon the upper ends of the arms 630 that form, with a yoke portion 632, a trunnion that is pivotally mounted upon a stud 634, the latter being supported in a bearing 636, 110 that projects outwardly from the supporting bracket 612. The yoke portion 632 of the trunnion is provided with an integral laterally projecting arm 638, the under side of which is provided with a socket 640 to receive one end of a coil spring 642, the lower portion of which is contained within an opening in a boss 644 that forms an integral part of the bracket 612. By reason of the action of the spring 642 upon the arm 638 115 120 125 130

downwardly. This downward movement permits the springs 692 to force the carriers 36 down into their initial positions.

The foregoing description pertains particularly to the construction and operation of those portions of the machine which function to automatically and progressively assemble a plurality of leather lifts in superposed relation to constitute heel piles that are subsequently attached to previously and extraneously formed leather-board heel blocks B to form complete heels composed of a section or block of leather-board and a section or heel-pile of leather. Obviously, any number of leather lifts may be so assembled by providing the requisite number of lift magazines 34, carriers 36, and picker members 46. Moreover, those portions of the machine hereinbefore described are equally applicable to the automatic building of entire heels of any desired material; that is, to heels that are complete in themselves and are not subsequently attached to other sections of leather-board or other material.

Having set forth the means and manner of automatically building the leather sections or heel piles, the apparatus by means of which these sections are measured and attached to previously and extraneously formed blocks of leather-board which form the base sections of the heels will now be set forth.

These previously and extraneously formed leather-board heel blocks B (Fig. 25) may comprise a plurality of flat lifts L that are polygonal in form and of graded sizes that are superposed the one upon the other with their breast surfaces in alignment whereby the heel portion and the sides of the blocks are stepped in formation. As shown in Fig. 25, each of the blocks B embodies a wedge-lift W that is inserted between the lowermost flat lift and the next adjacent lift of similar character. Thus, a wedge-block is produced. Obviously, any desired number, character and shape of lifts may be employed and the number of wedge-lifts may be increased if desired. The apparatus for and method of building these previously formed blocks B forms no material part of the present invention, except as the resulting blocks are employed as component parts of the completed heels that the machine is adapted to build. These blocks, of whatever character and shape, may, therefore, be previously and extraneously formed in any desired manner and are conveniently built through the agency of a machine which is mechanically associated with the machine of the present invention by means of the block-supply conveyor 56 that serves to feed the blocks B periodically and step-by-step to the present machine.

The block-supply conveyor 56 comprises a plurality of links or supporting plate 742 (Figs. 1, 4 and 25) that are pivotally connected by means of rods 744 that project through arms 746 which form parts of the links 742. The rods 744 project laterally beyond the several links and their ends are provided with cylindrical rolls 748. The rear end of each of the links or supporting plates 742 is provided with an upwardly projecting guide plate 750, against which the breast surface of the block is adapted to align. The chain conveyor 56 cooperates with and is supported upon a plurality of sprockets 752 that are rotatably mounted upon a shaft 754 that is journaled in bearings 756 and 758 (Fig. 4) that are suitably mounted upon the side pedestals 71 of the machine. The chain conveyor 56 is actuated step-by-step by any suitable means (not shown), whereby the previously formed blocks B are intermittently fed to the machine of the present invention.

In order to insure a uniformity of the completed heels that are built by the machine, each of the previously formed blocks B and the assembled and impaled heel piles upon the carriers 36 are measured before they are attached together. If either the block or the heel pile vary from predetermined dimensions the block and heel pile which were to have been united into a complete heel are both ejected from the machine. The apparatus for measuring and ejecting the blocks and heel piles will now be described.

The several blocks B are measured when they occupy a position directly above the sprockets 752, as shown in Figs. 25 and 26, while the gaging of the impaled heel piles is effected when the respective carriers 36 occupy the measuring station, as illustrated in Figs. 12 and 26.

Referring to Fig. 26, the several heel piles are gaged by means of a vertically reciprocable measuring pin 760 that is slidable in a bearing 762 that projects downwardly from the bed-plate 74 and is located beneath the heel pile upon the carrier in the measuring station. A spool 764 is threaded upon the pin 760 and may be positioned relative thereto by means of an adjusting knob 766. The spool 764 cooperates with a plurality of pins 768 that project inwardly between the flanges of the spool upon the opposite sides thereof and which are mounted in the respective arms 770 of a bifurcated lever 772. The lever 772 is pivotally mounted upon a stationary pin 774 that is carried in a bracket 776 upon a cross-beam 778 of the frame. The end of the lever 772 is pivotally connected to a rod 780 that is provided at its lower end with a longitudinally slotted member 782 and is biased to

its lower position by a spring 784 that is attached to the rod 780 and to a pin 786 in the cross-beam 788.

Mechanically associated with the slotted 5 end member 782 of the rod 780 is an arm 790 which forms a part of a lever that is rotatably mounted upon the shaft 134, the end of the arm 790 being provided with a pin 792 that loosely projects through the 10 slot in the end member 782. The lever, just referred to, is also provided with an arm 794 that carries a roll 796 which is adapted to cooperate with the cam 125 that is fixed to the main cam shaft 84. An arm 798 also 15 forms part of the above mentioned lever and is pivotally connected to one end of a rod 800, the other end of which has a pivotal connection to an arm 802. The arm 802 constitutes part of a bell-crank that is rotatably 20 mounted upon a stud 804 that is pivotally supported in a bracket 806, the opposite end of the stud 804 is provided with a plurality of arms 808 that are fixed thereto and are spaced apart and adapted to engage the 25 lower end of a block 810 which is fixed to a measuring rod 812. The block 810 is provided with a laterally projecting finger 814, and said measuring rod is slidably mounted for vertical movements in bearings 818 and 30 820 that are integral with a bracket 822, the latter being secured to the cross-beam 778. A plurality of collars 826 are fixed to the measuring rod 812, and one end of an arm 828 surrounds said rod between said collars. 35 The arm 828 is fixed to a rod 830, the purpose of which will be hereinafter set forth. The upper end of the rod 812 is provided with a laterally projecting ejecting and measuring finger 832 which has a down- 40 wardly extending portion 834. The finger 832 is adapted to engage the upper surface of the previously formed block B that is positioned above the sprockets 752, for the purpose of measuring the height of said 45 block, and said finger 832 is actuated downwardly into engagement with the block by means of a spring 836 that surrounds the lower end of the rod and acts against the bearing 818 and a nut 838 that is fixed to 50 the extremity of said rod. The measuring and ejecting finger 832 and the rod 812 are adapted for rotative movement, but are normally maintained in a predetermined position by means of a spring 840 that is con- 55 nected between an arm 842, constituting a part of one of the collars 826, and an arm 844 that is fixed to the hub of the arm 828, the latter arm being rigidly associated with the rod 830 and adapted only for vertical 60 movements. When the rod 812 and its associated measuring and ejecting finger 832 are rotated against the tension of the spring 840, in a manner that will be hereinafter set forth, the downwardly projecting portion 65 834 of the finger 832 is swung into engage-

ment with the breast surface of the block B above the sprockets 752, whereby said block is swept off and thus ejected therefrom.

In Fig. 26, the measuring pin 760 is illustrated in its lowermost or set position, while 70 the measuring finger 832 and the measuring rod 812, to which it is attached, are held in their uppermost or set positions, this relationship of elements being that of the measuring mechanism just prior to the gag- 75 ing operation and in which the roll 796 at the end of the arm 794 is on the point of dropping from the periphery of the cam 125 that is provided with a sharp drop 848. This drop 848 in the cam 125 permits a 80 counter-clockwise rotation of the associated arms 790, 794 and 798, whereby the springs 784 and 836 are respectively permitted to raise the measuring pin 760 into engagement 85 with the impaled heel pile upon the carrier 85 in the measuring station and to lower the measuring rod 812 and its associated measuring finger 832 into engagement with the previously formed block B above the sprockets 752. A plurality of stop fingers 847 and 90 849 (Figs. 12 and 26) is provided above the carrier in the measuring station to limit its upward movement at the time the measuring pin 760 is raised into engagement with the lower surface of the heel pile that is being 95 measured.

In order to effect the ejection of the block B by means of the swinging measuring and ejecting finger 832 when either said block or the impaled heel pile on the carrier 36 100 varies from predetermined dimensions, the following apparatus, which is dependent upon both concurrent measurements, is employed: The lever 772 is provided with an integral arm 850 which is pivotally connected by means of a link 854 to the end of an arm 851 that is fixed to a stud 856 which also carries a depending arm 852. The lower end of the arm 852 is connected to a slidable adjusting sleeve 858 by means 105 of a link 860. The adjusting sleeve 858 is adapted for longitudinal movement upon a rod 862 between a spool 864 and a collar 866, both of which are fixed thereto. The rod 862 is slidably mounted in bearings 868 110 and 870 that constitute parts of spaced arms of a bracket 872 which is fixed to the cross beam 778.

Another rod 874 of like construction is disposed parallel to the rod 862 and is also slide- 115 able longitudinally in the bearings 868 and 870. This latter rod is provided with a spool 876 and a collar 878 that are fixed thereto and also with a slidable adjusting sleeve 880 that is disposed between said spool and said 120 collar. The left hand ends (Figs. 26 and 27) of the rods 862 and 874 are engaged and restrained by means of friction stops 882. These stops 882 comprise small friction plates 884 that are disposed in open- 125 130

ings in bosses 886 which are integral with the bearing 870. The plates 884 are forced into frictional engagement with several gaging rods by means of springs 888 which 5 act upon the friction plates 884 and engage adjustable screw members 890 that are threaded into the ends of the bosses 886. The friction stops, just described, serve to restrain the rods 862 and 874 against 10 accidental movement.

The slideable adjusting sleeve 880 is connected to the upper end of a lever 892 through a link 894 and the lever 892 is pivotally mounted on a stud 896. The lever 892 is provided with an extension 898 that is pivotally connected to one end of a rod 900, the opposite end of which has a pivotal connection to an arm 902 that is integral with an arm 904 that forms a bell-crank 20 which is pivotally mounted upon the stud 804.

The arm 904 is disposed directly below the rod 830, the latter being adapted for vertical movement in bearings 912 and 914 that are 25 integral with the bracket 822. The rod 830 which, as hereinbefore stated, is mechanically associated with the measuring rod 812 by means of the arm 828, is adapted to be actuated in accordance with the movements of 30 said measuring rod. Therefore, as the measuring rod 812 and its associated finger 832 are lowered by the spring 836 into engagement with the block B, the rod 830 is correspondingly lowered and its lower end, 35 which is provided with an adjustable screw 916, is brought into engagement with the arm 904. By reason of this engagement, the arm 904 is rotated downwardly, which movement is transmitted to the slideable adjusting sleeve 880 through the intermediate 40 connections already described.

The spools 864 and 876 that are respectively fixed to the rods 862 and 874 are of like construction and are provided with V-shaped central grooves 918 that are adapted 45 to receive the wedge-shaped end 920 of a latch 922 which has a tail piece 924 that is pivotally mounted upon a pin 926. The pin 926 is surrounded by a torsion spring 50 928 that functions to maintain the wedge-shaped end 920 of the latch 922 in engagement with the spools 864 and 876.

The positions of the several spools 864 and 876 are determined by the operation of 55 the slideable adjusting sleeves 858 and 880, which in turn are dependent upon the movements of the measuring pin 760 and the measuring finger 832, as hereinbefore set forth. The relationship of parts is so chosen, or may 60 be obtained by suitable adjustments of the measuring pin 760 and the adjusting screw 916 of the rod 830, that the wedge-shaped end 920 of the latch 922 will drop into the V-shaped grooves 918 of the respective 65 spools 864 and 876 only when the height of

the impaled heel pile on the carrier and the height of the previously formed heel block B conform to predetermined dimensions. If the impaled heel pile varies from the prescribed height, the spool 864 is so positioned 70 that the wedge-shaped end 920 of the latch 922 is prevented from entering the V-shaped groove 918. Likewise, if the previously formed heel block B is too high or too low, the latch 922 is prevented from entering the 75 V-shaped groove 918 of the spool 876. It is only when the height of both the heel pile and the block are correct that the latch is permitted to enter the grooves 918 of the respective spools 864 and 876. 80

The purpose of this cooperative relationship of the respective spools 864 and 876 and the latch 922 is to determine the operation of that portion of the mechanism which is adapted to eject the heel blocks B 85 when either the heel pile or the heel block varies from the predetermined dimensions. The ejecting portion of the apparatus will now be set forth.

An ejecting rod 930 is positioned between 90 and below the rods 862 and 874, and is longitudinally movable in bearings 932 and 934, the bearing 934 being a part of the bracket 872 and the bearing 932 being suitably attached to the frame. The bearing 95 934 is provided with a friction restraining device 936 that is similar to the friction devices 882 already described, and serves to prevent accidental movement of the rod 930.

The ejecting rod 930 is moved to the left 100 (Fig. 26) or set by means of a setting sleeve 938 that is slideable thereon between fixed collars 940 and 942. Moreover, the sleeve 938 is provided with an upwardly projecting arm 944 that loosely surrounds the rods 105 862 and 874 and concurrently sets the adjusting sleeve 880 and the spools 864 and 876. The slideable setting sleeve 938 is connected by means of links 946 to the upper end of an arm 948 of a bell-crank 110 lever that is rotatably mounted upon the shaft 134 and has another arm 950 that carries a roll 952 which engages the periphery of the cam 129. The cam 129 is so constructed as to cause the setting sleeve 938 115 to be moved to the left to set the adjusting sleeve 880 and the rods 862 and 874 with their associated spools 864 and 876. Fig. 26 illustrates the relationship of parts under these conditions, and it will be noted 120 that said spools are so positioned that the wedge-shaped head 920 of the latch 922 rests upon the right-hand ends thereof. This is the set position of the spools 864 and 876, the measuring pin 760 and measuring finger 832, and corresponds to the largest size heel pile and heel block that can be engaged by the measuring mechanism. 125

The left-hand end of the ejecting rod 930 is provided with a notch 954 to receive the 130

end of the tail piece 924 of the latch 922. The rod 930 is secured to one end of a U-shaped yoke member 956 that extends laterally around an element of the machine to 5 be later set forth, and the right-hand end of the yoke member 956 is provided with a plurality of rods 958 and 960 that are disposed in parallel relation. In order to prevent the action of gravity upon the laterally projecting yoke member 956 from rotating the ejecting rod 930, said rod is provided with a fixed guide finger 957 which projects upwardly between the rods 862 and 874. The end of the rod 958 is so located 10 with respect to the finger 814 that is carried by the rotatably and longitudinally movable measuring rod 812 that engagement therewith may be effected when the measuring finger 832 is moved downwardly 15 20 from its raised position, shown in Fig. 26, into a measuring position in contact with the heel block B shown in Fig. 28. The end of the rod 960 is positioned so that it may be projected into engagement with a tail 25 piece 962 of a lever 964 that constitutes a part of the nailing mechanism 64, to be hereinafter described.

Assuming the component parts of the measuring mechanism 62 to occupy their 30 set positions, shown in Fig. 26, in which the measuring pin 760 is in its lowermost position and the measuring finger 832 is in its raised position, the operation of the measuring mechanism is as follows: As 35 the cam 129 is rotated in a counter-clockwise direction, the roll 952 drops from the projecting portion 966 of said cam and upon a surface 968. The bell-crank comprising the arms 948 and 950, therefore, is permitted 40 to be rotated in a clockwise direction by means of a spring 970, whereby the setting sleeve 938 is moved to the right out of engagement with the collars 866, 878 and 940 (Fig. 27) that are respectively associated with the rods 862, 874 and 930, thus 45 permitting a free movement of said rods if the occasion requires. Simultaneously with the drop of the roll 952 upon the surface 968 of the cam 129, the roll 796 is permitted 50 to move inwardly by reason of the drop 848 in the cam 125, the arm 794 upon which the roll 796 is mounted being actuated by means of a spring 972. This movement of the arm 794 effects a corresponding counter-clockwise movement of the arms 790 and 55 798 that are integral therewith. The downward movement of the arm 790 effects the disengagement of the pin 792 from the end member 782 of the rod 780, thereby permitting 60 the spring 784 to raise the measuring pin 760 through the agency of the intermediate lever 772 into engagement with the lower surface of the impaled and assembled heel pile upon the carrier 36 in the measuring 65 station. Similarly, the counter-clock-

wise movement of the arm 798 causes the fingers 808 to be withdrawn downwardly from the lower end of the block 810 that is associated with the measuring rod 812. The measuring rod 812, being thus unsupported, is forced downwardly by the spring 836 until the measuring finger 832 is brought into engagement with the upper surface of the heel block B. This movement brings the finger 814 of the block 75 810 opposite to the end of the rod 958 that is integral with the ejecting rod 930.

The upward gaging movement of the measuring pin 760 produces a movement of the adjusting sleeve 858 to the right through 80 the agency of the arm 850, the link 854, the arms 851 and 852, and the link 860. If the heel pile, being measured, is of the proper height, the right-hand end of the adjusting sleeve 858 is moved into engagement with 85 the collar 866 and actuates the rod 862 to the right to such a degree as to bring the V-shaped recess 918 of the spool 864 into registry with the wedge-shaped end 920 of the latch 922. If the heel pile is too high, the adjustment of the sleeve 858 is insufficient to engage the collar 866 and, therefore, the wedge-shaped end 920 of the latch 922 remains in engagement with the right-hand end of the spool 864. Should the heel pile 95 be less than the predetermined height, a relatively large movement of the adjusting sleeve 858 is effected which, by reason of the engagement with the collar 866, moves the spool 864 to such a position that its left-hand end engages and supports the wedge-shaped end 920 of the latch 922. It is evident, therefore, that the wedge-shaped end 920 of the latch 922 is brought into registry with the V-shaped groove 918 only when 105 the heel pile is of a predetermined height. Even then, the latch 922 is not permitted to drop into the V-shaped groove 918 unless the height of the heel block B is also correct, as will hereinafter appear. 110

Concurrently with the adjustment of the spool 864, which has just been described, the measuring finger 832 is dropped into engagement with the heel block B above the sprockets 752. In so doing, the measuring rod 812 is correspondingly lowered, which effects a corresponding movement of the finger 814 into a position in which it may be engaged by the end of the rod 958 that forms a part of the ejecting rod 930. Moreover, the rod 830 is similarly lowered by reason of the mechanical connection effected by the arm 828. The adjusting screw 916 on the lower end of the rod 830 is thus brought into engagement with the arm 904 115 of the bell-crank having another arm 902 that is connected by the rod 900, lever arms 898 and 892, and the link 894 to the adjusting sleeve 880. The sleeve 880 is, therefore, moved to the right in a manner similar to 120 125 130

that set forth in connection with the adjusting sleeve 858. This movement effects an adjustment of the spool 876 in accordance with the height of the heel block B, as will be understood. If the heel block B is of the proper height, the V-shaped groove 918 of the spool 876 is brought into registry with the wedge-shaped end 920 of the latch 922. Therefore, if the latch 922 is already 10 in registry with the groove 918 of the other spool 864, indicating that the heel pile is of proper dimensions, said latch is permitted to drop into the grooves 918 of both of the spools 864 and 876. In so doing, the 15 tail piece 924 of the latch 922 drops into the notch 954 of the ejecting rod 930, and said rod is thus restrained against movement to the right at the time when the roll 952, that is carried by the end of the arm 950, 20 passes over the drop 974 in the cam 129. As the cam 129 is rotated beyond the drop 974, therefore, the tail piece 924 of the latch 922 restrains the ejecting rod 930 against movement and also maintains the roll 952 25 free from the cam 129.

In the event, however, that the heel block B is too high, the movement of the adjusting sleeve 880 is insufficient to bring the groove 918 of the spool 876 into registry 30 with the wedge-shaped end of the latch 922, and, therefore, the right-hand end of said spool still engages the latch 922 and holds the tail piece 924 thereof out of the notch 954 of the ejecting rod 930, so that, irrespective 35 of the position of the spool 864 as determined by the height of the heel pile, the ejecting rod 930 is unrestrained. Similarly, if the heel block B is too low, the adjusting sleeve 880 is moved to the right to such 40 an extent that the left-hand end of the spool 876 engages the latch 922 and prevents it from restraining the ejecting rod 930.

From the foregoing description, it will be understood that the ejecting rod 930 is restrained only when both the heel pile and heel block are of predetermined dimensions. If, however, either one or both of the heel pile and heel block vary from predetermined dimensions, or are absent entirely, the spools 50 864 and 876 are so relatively positioned as to prevent the tail piece 924 of the latch 922 from dropping into the notch 954 and thus restraining the ejecting rod 930.

Assuming that the heel pile or heel block, 55 or both, vary from predetermined dimensions, and that the ejecting rod 930 is, therefore, unrestrained, said rod is projected to the right through the agency of the collar 942, sleeve 938, links 946, and the bell-crank 60 comprising the arms 948 and 950, when the drop 974 of the cam 129 passes beyond the roll 952. This projection of the ejecting rod 930 causes the end of its associated extended rod 958 to strike the finger 814 that is fixed 65 to the measuring rod 812. The measuring

rod 812, therefore, is given a sharp blow that swings the depending portion 834 of the measuring and ejecting finger 832 into contact with the breast portion of the heel block B being measured, whereby said heel block 70 is swept from the chain conveyor 56 and is thus ejected.

The ejection of the heel pile upon the carrier 36 of the measuring station, however, is not effected at this time, but the operation of 75 the machine is allowed to continue until the carrier upon which this particular heel pile is mounted is brought around the tracks 38 and 40 to the nail-loading station. At this station, and during the nail-loading operation, 80 the new nails N that are loaded into the carrier by means of the nailing pins 888 serve to drive out the previously loaded nails N upon which the particular heel pile is impaled. As soon as these nails are driven 85 from the carrier, the heel pile that is impaled upon said nails is thus freed from the carrier and is allowed to drop into a suitable waste container. It is thus evident that both the heel pile and the heel block are sooner or 90 later automatically ejected in the event that either one or both fail to meet the prescribed height requirements.

Having effected the measurement of the heel pile the heel block and the ejection 95 thereof, if conditions require it, the cams 125 and 129 continue to rotate until the rise 976 of the cam 125 forces the roll 796 to the outer periphery of said cam. This movement causes the arms 794, 790 and 798 to be 100 rotated in a clockwise direction, whereby the measuring pin 760 is lowered to its set position and the measuring finger 832 is raised to its corresponding position, as shown in Fig. 26, in which positions the measuring 105 and ejecting mechanism is in readiness for the next succeeding measuring operation. The adjusting sleeve 858, being mechanically associated with the measuring pin 760, is reset therewith.

When the rise 978 of the cam 129 is brought into engagement with the roll 952, said roll travels up said rise and causes the setting sleeve 938 to be moved to the left to engage the collars 866, 878 and 940 that are 115 respectively fixed to the rods 862, 874 and 930, whereby the spools 864 and 876, the ejecting rod 930, and the adjusting sleeve 880 and mechanically associated bell-crank arm 904 are again set into the positions indicated in Fig. 26.

After the completion of the measuring operation, the heel block B upon the supply conveyor 56 and which has just been measured, is transferred to the block carriage 60, 125 by means of which it is positioned beneath and in registry with the heel pile that has just been measured and which has subsequently been transferred to the nailing station. At this station, the heel block B is 130

raised into engagement with the lower surface of the heel pile upon the carrier 36 above it, and the nails N that extend downwardly from said carrier and upon which 5 the heel pile is impaled are driven into the heel block to permanently attach the heel pile thereto to form a complete heel. During this operation, the heel pile and the heel block are subjected to pressure. The mechanism for accomplishing the operation above 10 recited will now be described.

The successive heel blocks B that are intermittently fed to the machine upon the block supply conveyor 56 are successively 15 transferred in a lateral direction to the block carriage 60 by means of the transverse conveyor 58. This conveyor is illustrated best in Figs. 2, 4, 23 and 25, and comprises an endless chain 982 of any suitable form 20 that is supported upon sprockets 984 and 986 which are mounted at the right-hand end of the machine upon the respective shafts 985 and 987 having bearings that are associated with the upright bracket 79. At 25 equally spaced intervals on the chain 982, outwardly extending fingers 988 are provided, said fingers being pivotally mounted upon pins 990 that project laterally from the respective sides of the chain and form parts 30 thereof. Each of the fingers 988 is provided with angularly disposed arms 992, the outer ends of which are provided with pivotally mounted rolls 994, and said rolls are adapted to travel in a pair of spaced and grooved 35 tracks 996 that are located on the respective sides of the chain 982. The inner track 996 is suitably mounted upon the upright bracket 79 on the frame of the machine and the outer track is supported from the inner 40 track by means of transverse supporting arms 998. By reason of the cooperative engagement of the rolls 994 with the respective tracks 996, the fingers 988 are always maintained at substantially right angles to 45 the chain. The position of the sprocket 984 is such that as the fingers 988 are carried around the sprocket, they are brought into engagement with one side of the successive heel blocks B whereby said blocks are moved 50 laterally from the block supply conveyor 56 to the block carriage 60, as will be more fully set forth.

The chain 982 is intermittently driven in proper timed-cooperation to the other elements of the machine by means of a Geneva gear of well-known construction that comprises a radially slotted plate 1000 that is fixed to the same shaft 987 that carries the sprocket 986. This plate is provided with 55 pairs of diametrically disposed slots 1002 that are positioned at right angles to one another, and the periphery of the intervening sectors are recessed to form portions of circular surfaces 1004. Cooperating with 60 the slotted plate 1000 is a circular driving

member 1006 of the same diameter as that of the circular surfaces 1004 and which is adapted to cooperate with said surfaces during certain portions of the operation. The circular driving member 1006 is mounted 70 upon a shaft 1008 that is mounted in the upright brackets 78 and 79 and is provided with a fixed arm 1010, the end of which carries a driving pin 1012. The periphery of the circular driving member 1006 is recessed 75 adjacent to the arm 1010 to form a circular surface 1014 to permit of rotative movement of the slotted plate 1000 when the circular driving member 1006 and its associated driving pin 1012 are rotated in such manner as to position the pin 1012 within one of the radial slots 1002.

The circular driving plate 1006 is driven continuously in a manner to be set forth, and at each revolution thereof, the pin 1012 is 80 brought into engagement with the sides of one of the radial slots 1002 of the slotted plate 1000 and effects a rotative movement thereof through a quarter turn. Thus, having rotated the slotted plate 1000 in 85 this manner, said plate remains at rest for a predetermined interval until the pin 1012 is again brought into cooperative engagement with the edges of the next slot 1002 of said plate. Thus, the 90 sprocket 986, together with the chain 982 and its associated fingers 988, are intermittently actuated step-by-step and, at each step, a heel block B is transferred laterally from the block supply conveyor 56 to the 95 block carriage 60.

The continuous rotation of the circular driving member 1006 is effected by means of a sprocket 1016 (Figs. 2 and 4) that is fixed to the shaft 1008 and which is engaged by a 100 driving chain 1018 that passes over idler sprockets 1020 and 1022 and is driven by a sprocket 1024 that is fixed to the main cam shaft 84 of the machine. The idler sprockets 1020 and 1022 are adjustably mounted to the 105 frame and may be employed for determining the tension of the driving chain 1018 as well as for positioning the same.

Referring particularly to Figs. 4, 16, 23, 24 and 25, the block carriage 60 comprises 110 an extended horizontally disposed bed-plate 1026 that is rigidly positioned upon a vertically disposed supporting post 1028, and said bed-plate is provided with laterally projecting longitudinal flanges 1030. A 115 sliding frame 1032 having a rectangular central opening rests upon the bed-plate 1026 and its side portions are provided with inner longitudinal grooves to receive the flanges 1030 thereof. Mounted upon the 120 right-hand end (Figs. 16 and 24) of the sliding frame 1032 is an upwardly projecting guide finger 1034, having a wedge-shaped end 1036. A plurality of beveled 125 guide fingers 1037 and 1038 are provided at 130

the respective sides of the left-hand end of the sliding frame 1030, and said guide fingers, together with the guide finger 1034, serve to cooperate with and position the 5 carrier during the nailing operation, as will hereinafter appear. The guide fingers 1037 and 1038 respectively support inwardly projecting stop arms 1040, which are secured thereto and against which the breast 10 surfaces of the several heel blocks B are positioned and aligned during the operation of the block carriage.

A plate 1044, upon which the heel blocks B are supported after being transferred by 15 the transverse conveyor 58, rests upon the sliding frame 1032 and is loosely positioned between the respective ends thereof. The right-hand end of the plate 1044 is provided with an upwardly projecting portion 1046 20 having an inner face of curved contour to engage the heel portion of the heel blocks B and assist in aligning them against the stop arms 1040 during the operation of the block carriage. The right-end of the plate 1044 is 25 pivotally connected to the left-hand end of the sliding frame 1032 by means of a plurality of links 1048 that are located on the respective sides of said sliding frame. A wedge-plate 1047 is secured upon the upper 30 surface of the left-hand end of the bed-plate 1026 and serves to tilt up the loosely positioned block supporting plate 1044 when the block carriage is moved into the nailing station, whereby the upper surface of the 35 block is brought into a horizontal plane prior to the nailing operation.

In order to center the heel blocks B laterally upon the plate 1044, angular centering arms 1050 and 1052 are provided. The centering arm 1050 is fixed to one end of a rack 40 1054 that projects laterally beneath the bed-plate 1026, while the centering arm 1052 is associated with the opposite end of a rack 1056 that is similarly positioned beneath the 45 bed-plate 1026 and in parallel relation to the rack 1054. A pinion 1058 is pivotally mounted intermediate the racks 1054 and 1056 and is adapted to cooperate therewith, whereby said racks are actuated concurrently. The other end of the rack 1056 is 50 pivotally connected to an arm 1060 (Figs. 16, 24 and 26) of a bell-crank having another angularly disposed arm 1062 integrally associated therewith. The bell-crank, just referred to, is pivoted upon a pin 1064 that is 55 carried by an integral portion 1066 of the bed-plate 1026. This bell-crank is further provided with an arm 1068 that is engaged by a pin 1070 that is positioned in an opening 60 in the integral portion 1066 of the bed-plate 1026. The pin 1070 is maintained in yielding engagement with the arm 1068 by means of a spring 1072, whereby the centering arms 1050 and 1052, that are respectively 65 associated with the racks 1054 and 1056, are

normally maintained in gripping relation to the heel block that is positioned upon the supporting plate 1044.

The sliding frame 1032 and the heel block supporting plate 1044 which rests thereon 70 are initially positioned at the right-hand end of the bed-plate 1026 in order to receive a heel block as it is transferred thereto by the transverse conveyor 58, and, in order to assist in positioning the heel block during the 75 transferring operation, a U-shaped guide member 1074 is located in the line of movement of the blocks and is supported upon an arm 1076 that is secured to the side pedestal 71. The U-shaped guide member 1079 has 80 inclined side portions 1078 and 1080, upon which the blocks slide in being moved to and from the block carriage 60.

The longitudinal actuation of the sliding frame 1032 and the associated loosely 85 mounted block supporting plate 1044 from the outer or block-receiving position to the inner or nailing position beneath and in registry with the carrier which occupies the nailing station, is effected by means of a 90 longitudinally disposed pull rod 1082 (Fig. 24). The right-hand end of the pull rod 1082 is provided with a T-shaped head 1084 that is loosely disposed within a suitable slot in the left-hand end of the sliding frame 95 1032, and is adapted for relative vertical movements with respect thereto in order to permit of the elevation of the block carriage 60 during the nailing and pressing operation, as will hereinafter appear. The 100 pull rod 1082 extends through a guide member 1088 that is secured to the lower side of the main bed-plate 74 of the machine, and also projects through openings in arms 1090 and 1092 of a member 1094 that forms 105 a continuing section of the pull rod 1082. Between the arms 1090 and 1092, the pull rod 1082 is provided with a block 1098 that is adjustably fixed thereto by a set screw 1100 and which is provided with an opening 110 through which the member 1094 loosely extends. A coil spring 1102 is disposed around the pull rod 1082 and its respective ends engage the arm 1090 of the member 1094 and the block 1098 that is secured to 115 said pull rod. Thus, a yielding connection is established between the rod section 1094 and the pull rod 1082. The rod section 1094 and the rod 1082, in effect, constitute a single member having an intermediate 120 yielding connection, and hereinafter these two component rod sections will be considered together as the pull rod 1082.

The pull rod 1082, as a whole, extends substantially the length of the machine beneath the bed-plate 74, and its left-hand end has a pivotal connection to a lever 1104, the lower end of which is pivotally connected to an arm 1106 (Figs. 3 and 5) that forms an integral part of the bell-crank 130

comprising the arms 302 and 306. Intermediate the ends of the lever 1104, a pivotal connection is provided with a link 1108, said link being pivotally mounted upon a 5 bracket 1110 upon the frame.

By reason of the connections just described, it is evident that the block-supporting plate 1044 and the block B disposed thereon are actuated inwardly into the nail- 10 ing station at each return outward movement of the shaft 274 with which is associated the sleeve 280 that is provided with the fingers 284 for engaging and actuating the several carriers 36 through the successive 15 assembling stations. In the event of a non-uniformity in the lengths of the several heel blocks B that are handled by the block carriage 60, variation in sizes are accommodated by means of the yielding connection that 20 has been described as interposed between the respective component sections of the pull rod 1082. Obviously, the return outward movement of the block-supporting plate 1032 is effected at the time that the several 25 carriers are advanced from one assembling position to another by the shaft 274 and associated sleeve 280 above referred to.

As has been hereinbefore stated, the bed-plate 1026 and, therefore, the block carriage 30 as a whole, is supported upon the post 1028. The upper portion of the post 1028 is rectangular in section and is vertically slidable within a guide member 1112 that is bolted to a cross beam 778 of the frame. The re- 35 maining portion of the post 1028 is of cylindrical form, and its lower end is slidably positioned in a bearing 1116 formed in the cross beam 788. A collar 1118 is pinned to the lower end of the post 1028, and above 40 said collar, the post is provided with a loosely mounted sleeve 1120 that engages and supports the lower end of a compression coil spring 1122, the upper end of which en- 45 gages a shoulder at the lower end of the rectangular portion of the post 1028. The sleeve 1120 is suspended by means of a link 1124 from an arm 1126 that is pivotally mounted upon the shaft 134 of the machine. The arm 1126 carries a roll 1130 that travels 50 upon the cam 127 that is fixed to the main cam shaft 84. The cam 127 is designed to periodically raise the roll 1130, whereby the arm 1126 is actuated, to the end that the post 1028 and the block carriage 60 that is 55 associated therewith is elevated through the agency of the link 1124, the sleeve 1120 and the compression spring 1122. In this manner, the heel block B that rests upon the block supporting plate 1044 of the block 60 carriage 60 is raised into engagement with the lower surface of the impaled heel pile upon the carrier 36 which occupies the nail- 65 ing station.

The means for gripping and centering 65 the heel blocks B upon the block supporting

plate 1044 through the agency of the centering members 1050 and 1052 has already been described. This gripping and centering means, however, becomes effective only when the block carriage 60 and the post 70 1028 upon which it is mounted, are raised from their lower initial position, in which position the centering arms 1050 and 1052 are maintained in their released position by reason of the engagement of the arm 1062 75 with an adjustable stop 1136. The stop 1136 is carried upon an arm 1138 that forms a part of a bearing member 1140, which itself is integrally associated with a bracket 1141, the latter being secured to the cross 80 beam 778 by the same bolts that serve to position the guide member 1112. The engagement of the arm 1062 and the stop 1136 causes the arm 1068 to be rotated in a clockwise direction, whereby the normal ac- 85 tion of the spring 1072 is overcome, thus permitting a concurrent release movement of the racks 1054 and 1056 upon which the centering arms 1050 and 1052 are respec- 90 tively mounted. As soon, however, as the post 1028 and the block carriage 60 are raised from their lowermost positions, in the manner already set forth, the arm 1062 is elevated to disengage the stationary stop 1136 whereby the spring 1072 is permitted to 95 actuate the centering arms 1050 and 1052 into their gripping and centering positions upon the heel block. Obviously, when the heel block carriage 60 is again lowered, the engagement of the arm 1062 with the sta- 100 tionary stop 1136 is again effected, whereby the block is released, as will be understood.

During the raising operation of the block carriage 60 and the block that is supported thereon, the tapered guide arm 1034 pro- 105 jects through the slot 251 in one end of the carrier 36 that occupies the nailing station, while the tapered guide arms 1037 and 1038 cooperate with the opposite sides of the other end of the carrier. Thus, the carrier 110 and the block carriage are caused to occupy a definite relationship the one to the other, so that the impaled heel pile upon the carrier and the heel block B upon the block carriage are brought into registry with 115 their respective breast surfaces in alignment.

After having raised the block carriage 60 and the heel block B to their uppermost positions, they are temporarily and positively locked therein during the nailing operation, 120 to be hereinafter set forth, by means of a clutch 1142 (Fig. 26). This clutch comprises a roll 1144 that is positioned adjacent to and in engagement with one side of the rectangular section of the post 1028, said 125 roll being located in a suitable opening in the guide block 1112. The roll 1144 is also adapted to have a cooperative engagement with a plate 1146 that is secured to one side of the recess in the guide block 1112 and is 130

disposed at a slight angle to the post 1028 in such position as to permit the roll 1144 to be wedged firmly between said plate 1146 and said post 1028. A pin 1148 having a head 1150 is located within the recess in the 5 guide block 1112 and is forced downwardly upon the roll 1144 by means of a spring 1152. Thus, there is a constant tendency to maintain the roll 1144 in its lowermost position 10 and in gripping relation to the post 1028, although any upward movement of said post raises the roll 1144 slightly, whereby its restraining action is overcome. The post 1028, therefore, may be freely raised 15 but is immediately locked in position thereafter by means of the clutch just described.

Assuming the block carriage 60 and the post 1028 to be locked in their raised positions in the manner just set forth, the release 20 thereof is accomplished by a release bar 1154 that is positioned adjacent to the post 1028 and is adapted for vertical movements to bring its upper end into engagement with the roll 1144, in order to slightly 25 raise the roll from its gripping position and permit the post 1028 to be lowered. The release bar 1154 rests upon the outer end of an arm 1156 that is pivotally mounted upon a stud 1158 upon the frame, and said arm 30 1156 has a depending lug 1160 that rests upon a lug 1162 that forms a part of an arm 1161 which is rotatably supported upon the shaft 134. The arm 1161 carries a roll 1163 that travels on the cam 126 fixed to 35 the cam shaft 84. The release of the clutch 1142, therefore, depends directly upon the configuration of said cam which is designed to raise the arm 1161 and, therefore, the arm 1156 and release bar 1154, in proper 40 timed cooperation with the other elements of the machine in order that the clutch 1142 shall be released after each nailing operation has been completed.

Assuming the heel block B to be raised 45 and locked in engagement and registry with the heel pile that is impaled upon the downwardly projecting nails N of the carrier 36 that occupies a nailing station, the nailing mechanism 64 is brought into play.

The nailing mechanism 64 comprises a vertically reciprocable nailing block 1164 (Figs. 2, 23, and 26) that is slidable within a guide member 1166 that is suitably bolted between the upright brackets 78 and 79. The 55 lower end of the nailing block 1164 is provided with a head 1168, which carries a plurality of nailing pins 1170 that are so spaced apart as to engage the heads of the nails N that are held between the gripping jaw 60 members 230 of the carrier 36 that occupies the nailing station. The upper portion of the head 1168 of the nailing block 1164 is pivotally connected to the lower end of a link 1172 that forms, with a link 1174 that is pivotally 65 mounted upon the shaft 724, an operating

toggle. The aforesaid links 1172 and 1174 have their other ends pivotally associated by means of a stud 1176, and one end of a link 1178 also has a pivotal connection with the stud 1176. The other end thereof is pivotally mounted on the lower end of an arm 1180 that, with an arm 1182, forms a bell-crank which is pivotally supported upon a shaft 1184, the latter being carried by the upright brackets 78 and 79. The outer end 70 of the arm 1182 has a pivotal connection to the upper end of a nailing rod 1186.

Referring particularly to Figs. 28 and 30, the lower end of the nailing rod 1186 is positioned and guided by a bearing 1188 that 80 is pivotally mounted within a recess in the cross-beam 788 upon pivot pins 1190 that project through the sides of said recessed cross beam, the latter being secured to the cross-beam 73 by means of bolts 1194. Above 85 the bearing 1188, the lower end of the nailing rod 1186 is provided with a slidable sleeve 1196 that is positioned between fixed collars 1198 and 1200 and is adapted for vertical reciprocable movements. The slidable sleeve 1196 is pivotally supported by a pin 1202 to the upper end of a link 1204, having its lower end pivoted to an arm 1206 that is rotatably mounted upon the shaft 134 (Fig. 26) and carries a roll 1208 intermediate its ends. The roll 1208 rides in a cam path upon the cam 128 that is fixed to the main cam-shaft 84 and said cam is designed and angularly disposed upon the cam shaft 84 to effect periodic vertical movements of the sleeve 1196. 90

Under normal conditions, when the heights of the heel block B and heel pile upon the carrier 36 in the measuring station are correct and the heel pile is to be attached to the heel block, a distance block 1210 of U-shaped section is maintained in position beneath the sliding sleeve 1196 and between it and the fixed collar 1200 to establish an operative connection between said sleeve and the nailing rod 1186, in the following manner: The distance block 1210 forms an integral 105 part of the lower end of the S-shaped curved lever 964 that is fixed to one end of a pin 1212 that is carried by a rib 1214 of the slidable sleeve 1196. The other end of said pin is provided with the fixed arm or tail piece 962 that has been hereinbefore referred to as located in the path of travel of the end of the rod 960 which is rigidly associated with the ejecting rod 930. 110

The pin 1212 is surrounded by a torsion spring 1216 which tends to maintain the distance block 1210 in its inner position, where it establishes an operative connection 115 between the sliding sleeve 1196 and the nailing rod 1186. The distance block 1210 is provided with a pin 1220 that projects into a cam slot 1222 within a cam 1224. The cam 1224 is fixed to a pin 1226 that is rotatably 125

130

carried by the frame, and said pin 1226 is provided with a rigidly secured latch 1228 that normally is withdrawn from the collar 1200 by means of the torsion spring 1216 5 acting through the lever 964 and the cam 1224, whereby the nailing rod 1186 is free to be moved downwardly to actuate the nailing block 1164.

Assuming that the heights of the heel 10 pile and heel block that are being gaged by the measuring mechanism, are found to be correct, in which case the ejecting rod 930 is restrained by the latch 922 the distance block 1210 is maintained in position 15 between the sliding sleeve 1196 and the fixed collar 1200 to entirely fill the space between the fixed collars 1198 and 1200, and the latch 1228 is withdrawn from beneath the fixed collar 1200. Under these circumstances, 20 the nailing rod 1186 is free to be actuated in a downward direction by means of the arm 1206 in accordance with the operation of the cam 128 upon the main cam shaft 84. This downward movement of the 25 nailing rod 1186, through the arms 1180 and 1182 of the bell-crank and the link 1178, forces the operating toggle, comprising the links 1172 and 1174, into dead center position whereby the nailing block 1164 is forced 30 downwardly, as will be understood. The nailing pins 1170, that are secured to the head 1168 of the nailing block, are thus brought into engagement with the heads of the nails N that are gripped in the carrier 35 36 in the nailing station, whereby said nails are forced entirely through the carrier and free from the gripping jaw members 230. Moreover, the nails N are driven into the block B, and the heel pile is thus permanently attached thereto to form a completed 40 heel. Subsequently, the cam 128, through the agency of the arm 1206 and slideable sleeve 1196, raises the nailing rod 1186 and the nailing block 1164 to their initial positions. A plurality of stop fingers 1229 45 (Figs. 4, 12, 23 and 25) are positioned just above the carrier in the nailing station for the purpose of maintaining it in position as the nail driven pins 1170 are withdrawn 50 through the gripping jaw members of the carrier.

It will be understood that during the nailing operation, the heel block and the heel pile are supported upon the block carriage 55 60, which is locked in its uppermost position by the clutch 1142, thus providing a rigid support while the nails N are being driven from the carrier and into the heel block.

In the event that the height of either the 60 heel pile or the heel block that are being engaged by the measuring mechanism is found to be incorrect, the ejecting rod 930 is unrestrained by the latch 922 and is actuated to the right to cause the end of 65 the rod extension 960 to be projected

against the tail piece 962 of the lever 964 that carries the distance block 1210. By reason of this engagement, the lever 964 with the associated distance block 1210, is moved outwardly against the action of the torsion spring 1216, whereby the distance block 1210 is withdrawn from beneath the 70 slideable sleeve 1196.

Under these circumstances, it is evident that the operative connection between the reciprocating sliding sleeve 1196 and the nailing rod 1186 is interrupted, and the sliding sleeve 1196 is permitted to be reciprocated freely between the fixed collars 1198 and 1200. The outward movement of the 80 distance block 1210 also actuates the cam 1224 outwardly by reason of the pin-and-slot connection between them. Consequently, the latch 1228 is moved into position beneath the fixed collar 1200, whereby 85 the nailing rod 1186 is supported, and hence the downward operative stroke of the nailing block 1164 is prevented.

The distance block 1210 is held in its outer or removed position by the continued 90 engagement of the tail piece 962 with the end of the rod 960, which rod constitutes a part of the ejecting rod 930 that is temporarily maintained in its right-hand or projected position (Fig. 26) by means of 95 the friction stop 936. When the ejecting rod 930 is re-set to its initial left-hand position by means of the setting sleeve 938, the link 946, the arms 948 and 950, and the roll 952 that cooperates with the cam 129, the torsion spring 1216 that surrounds the pin 1212 returns the distance block 1210 beneath the 100 sliding sleeve 1196 to its normal position. Thus, the operative connection between the slideable sleeve 1196 and the nailing rod is 105 re-established, and the nailing mechanism is in readiness for the next nailing operation.

It is desirable not only to nail the heel pile to the heel block but also to subject both component sections of the heel to considerable pressure during the nailing operation. It is also desirable to provide means for adjusting the pressure to which the heel blocks and heel piles are subjected, in order to adapt the machine to build heels of different heights and other characteristics, and since the working stroke of the nailing block 1164 is constant, this adjustability of pressure is attained by suitable means associated with the vertically reciprocable block 115 carriage 60 now to be described.

The integral part 1066 of the bed-plate 1026 of the carriage is provided with a downwardly extending threaded rod 1230 (Fig. 25). This rod 1230 projects loosely through the stationary bearing member 1140 and its lower threaded end is provided with a plurality of adjustable nuts 1232.

For any given heel, composed of a heel pile and a heel block of predetermined di- 130

- mensions, it is evident that no pressure will be applied to the component parts thereof if the adjusting nuts 1232 are so positioned as to permit the block carriage 60 to be raised 5 to a height which just brings the upper surface of the heel block that is supported thereon into engagement with the lower surface of the heel pile upon the carrier in the nailing station. With such an adjustment, 10 the downward working stroke of the nailing block 1168 is just sufficient to drive the nails N free from the carrier and into the heel block until their heads are flush with the upper surface of the heel pile.
- 15 Obviously, to subject the heel pile and the heel block to pressure, it is necessary to position the adjusting nuts 1232 slightly below the assumed adjustment above referred to. In this event, the block carriage 60 is 20 raised slightly above the position assumed, and is locked therein by the clutch 1142. Therefore, the working stroke of the nailing block 1168 serves not only to drive the nails N but also to apply pressure to the super- 25 posed heel pile and heel block. The degree of pressure may be adjusted as desired by suitably setting the adjusting nuts 1232, which limit the upward movement of the block carriage 60, as will be understood.
- 30 The length of the coil spring 1122 that surrounds the post 1028 is such as to raise the block carriage 60 to a height sufficient to accommodate the lowest heels that the machine is adapted to build. When the machine 35 is set to build heels of any greater heights, which necessitates a correspondingly lower locked position of the block carriage 60, which position is determined by the limiting adjusting nuts 1232, the excess upward travel of the sliding sleeve 1120 that surrounds the post 1028 is taken up by the yielding of the spring 1122, as will be understood. Obviously, the greater the height of the heels built, the lower is the locked position 40 of the block carriage, and therefore the greater is the compression of the spring 1122. Manifestly, by suitably setting the adjusting nuts 1232, the machine may be adapted to build heels of any desired height within 45 the limits of its construction and to subject the heels to any desired amount of pressure.
- Assuming the nailing operation to have been completed, the nailing block 1164 is subsequently raised, and, concurrently therewith, 55 the release bar 1154 effects the release of the clutch 1142 in the manner already set forth, whereby the block carriage 60 is free to be lowered into its initial position through the agency of the cam 127, which is designed 60 to effect this operation in the proper timed cooperation with the other elements of the machine.
- After having lowered the block carriage 60 and the completed heel that has just been 65 nailed and subjected to pressure, the pull rod 1082 actuates said carriage outwardly to its initial block-receiving position. The completed heel, therefore, is carried outwardly into a position in the path of travel of the fingers 988 of the transverse block 70 conveyor 58. Hence, as said conveyor effects its next succeeding step of actuation, the completed heel upon the block carriage 60 is moved down the inclined side portion 1080 of the U-shaped guide member 1074 and 75 upon the heel removal conveyor 66, by which the successive completed heels are transported from the machine to any suitable receptacle or desired location.
- The heel removal conveyor 66, as shown, is 80 similar in construction to the block supply conveyor 56 and may be actuated intermittently or continuously in any desired manner. Like the block supply conveyor 56, the heel removal conveyor 66 may conveniently comprise a plurality of links, which are adapted to cooperate with and be supported by a plurality of sprockets 1236 that are positioned upon the shaft 754 which, as has already been set forth, is mounted on the right-hand 85 side of the machine in the bearings 756 and 758.
- At the same time that the completed heel is removed from the block carriage 60 and transferred to the heel removal conveyor 66, 90 the next succeeding heel block B that is disposed upon the block supply conveyor 56 directly above the sprockets 752 is transferred transversely to the block carriage 60 that has just been vacated by the completed heel, the 95 transfer of the heel block being effected by one of the fingers 988 of the transverse conveyor 58.
- The nature and scope of the present invention having been indicated, and the preferred embodiment of the invention having been specifically described, that which is claimed as new is:
1. A heel-building machine having, in combination, a plurality of lift holders, 110 supporting means upon which the heels are assembled, and a plurality of picker members, corresponding in number to the component lifts of the heels to be built, for concurrently transferring lifts from the respective lift holders to said supporting means and retaining control thereof until they are deposited thereon.
  2. A heel-building machine having, in combination, a plurality of lift holders, supporting means upon which the lifts are assembled, means for intermittently moving said supporting means, a plurality of picker members, corresponding in number to the component lifts of the heels to be built, for 120 periodically and concurrently transferring lifts from said lift holders to said supporting means, and means for securing together the assembled lifts.
  3. A heel-building machine having, in 125

combination, a plurality of lift holders, a plurality of intermittently movable carriers upon which the lifts are assembled, and means including a plurality of picker members, corresponding in number to the component lifts of the heels to be built, for severally taking single lifts from the respective holders and definitely positioning them upon the respective carriers.

10 4. A heel-building machine having, in combination, a plurality of lift holders, a plurality of carriers upon which the lifts are assembled, and a plurality of interconnected picker members adapted for concurrent parallel movements in the same plane for transferring lifts from the respective lift holders and placing them in definite positions upon the respective carriers.

5. A heel-building machine having, in combination, a plurality of lift holders, supporting means upon which the lifts are assembled, and a plurality of movable picker members corresponding in number to the component lifts of the heels to be built disposed in the same plane and adapted to be moved back and forth concurrently between said lift holders and said supporting means and comprising means for picking lifts from the respective holders, and while retaining control thereof depositing them in definite positions upon said supporting means.

6. A heel-building machine, having in combination, a plurality of lift holders, a plurality of intermittently movable carriers upon which the lifts are assembled, and a plurality of movable picker members corresponding in number to the component lifts of the heels to be built disposed in the same plane and adapted to be moved back and forth concurrently between said lift holders and said carriers and comprising lift-engaging members severally associated therewith, means for causing said lift-engaging members to engage the exposed lifts in the respective holders, and means for depositing the lifts upon the respective carriers and subsequently releasing the lift-engaging members therefrom.

7. A heel-building machine having, in combination, a series of lift holders, supporting means, upon which lifts are assembled in superposed relation, a plurality of picker members, corresponding in number to the component lifts of the heels to be built, for periodically and concurrently transferring lifts from the respective lift holders and while retaining control thereof depositing them in definite positions upon the supporting means, and means for securing together the assembled lifts.

8. A heel-building machine having, in combination, a row of lift holders and a row of movable carriers disposed in parallel relation, a plurality of picker members, corresponding in number to the component lifts

of the heels to be built, adapted to travel transversely to said rows of lift holders and carriers for periodically and concurrently transferring lifts from the respective lift holders and definitely positioning them upon the respective carriers to form heels, and means for pasting together the lifts of the assembled heels.

9. A heel-building machine having, in combination, a row of holders for stacked lifts of graded characteristics, intermittently movable supporting means upon which the lifts are progressively assembled, a plurality of picker members, corresponding in number to the component lifts of the heels to be built, acting during periods of rest of said movable supporting means for intermittently and concurrently transferring lifts from the respective holders and depositing them upon the supporting means, and means for pasting together the assembled lifts.

10. A heel machine having, in combination, a plurality of unconnected carriers for supporting heel piles and each capable of independent movement, means for supporting said carriers, and means for periodically and concurrently engaging a portion only of said carriers and moving said portion thereof through predetermined distances.

11. A heel machine having, in combination, a plurality of unconnected carriers for supporting heel piles and each capable of independent movement, means for supporting said carriers, means for engaging a portion only of said carriers and concurrently actuating said portion thereof through predetermined distances, and separate means cooperating with each carrier of said portion for locking it positively in position.

12. A heel-building machine having, in combination, a plurality of unconnected carriers upon which heels are assembled, said carriers being capable of independent movement, means for supporting said carriers, and reciprocating means concurrently cooperating with each of a portion only of said carriers for engaging the carrier, moving the carrier a predetermined distance, disengaging the carrier, and returning to its initial position.

13. A heel-building machine having, in combination, a plurality of unconnected carriers upon which heels are assembled, each carrier being capable of independent movement, means for supporting said carriers, a member having a plurality of spaced fingers, means for moving said fingers into and out of engagement with a portion only of said carriers, and means for longitudinally moving said member to actuate said portion of said carriers through predetermined distances and for returning it to its initial position.

14. A heel machine having, in combination, a plurality of independent and individ-

- ual carriers for supporting and carrying heel piles, and automatic means for acting upon said carriers independently and for actuating one of said carriers in different 5 manners at different times.
15. A heel machine having, in combination, a plurality of independent and individual carriers for supporting and carrying piles of superposed lifts, and means for currently 10 actuating said carriers in different angularly disposed planes.
16. A heel machine having, in combination, a plurality of independent and individual carriers for supporting heel piles and carrying them through a plurality of stations, and means for actuating said carriers at a different rate of speed between certain stations than between others.
17. A heel machine having, in combination, a plurality of independent and individual carriers for supporting piles of superposed lifts and carrying them through a plurality of stations, automatic means for independently 15 actuating said carriers in one plane through all of said stations, and automatic means for actuating the carriers at certain stations in another plane.
18. A heel machine having, in combination, a plurality of independent and individual carriers for supporting piles of superposed lifts and carrying them through a plurality of stations, a track upon which the carriers travel, means for periodically and independently engaging and actuating the 20 carriers along the track, and means for moving the carriers vertically with respect to the track at a certain station.
19. A heel machine having, in combination, a plurality of unconnected movable carriers, each adapted for independent movement, means for positively actuating of a portion only of said carriers step by step through successive stations, and other means for positively engaging and locking each of said portions of said carriers in the 25 respective stations.
20. A heel building machine having, in combination, a plurality of unconnected movable carriers, each adapted for independent movement, a reciprocable and rotatable member having projecting arms adapted to concurrently and positively engage a portion only of said carriers and actuate said portion thereof step by step 30 through successive stations, and a rotatable member having projecting arms adapted to concurrently and positively engage and lock each of said portions of said carriers in the successive stations.
21. A heel machine having, in combination, a plurality of blank holders, a plurality of independently movable unconnected carriers upon which blanks are deposited, means for intermittently moving a portion 35 only of said carriers, and intermittently operable means for transferring blanks from said holders and depositing them upon the respective carriers.
22. A heel machine having, in combination, a plurality of independent carriers for supporting piles of superposed lifts, a plurality of endless supporting tracks on which the carriers travel, and means for concurrently engaging and individually actuating said independent carriers.
23. A heel machine having, in combination, a movable carrier for supporting heel piles, an endless supporting and guiding track therefor, an endless conveyer, and means operable at a predetermined point of said track for causing said conveyer to engage and actuate said carrier along a portion of said track and for disengaging said carrier at another point of said track.
24. A heel machine having, in combination, a movable carrier for supporting heel piles, a supporting and guiding track therefor, a conveyer for actuating said carrier along a portion of said track, and other means for actuating said carrier along another portion thereof.
25. A heel-building machine having, in combination, a movable carrier on which heel lifts are assembled, a supporting and guiding track therefor, a conveyer for continuously actuating said carrier along a portion of said track, and other means for intermittently actuating said carrier through a plurality of assembling stations along another portion thereof.
26. A heel machine having, in combination, a movable carrier for supporting a heel pile, an endless supporting and guiding track therefor, a continuously operating endless conveyer, means associated with said conveyer, for normally engaging said carrier and actuating it along said track, means for effecting a disengagement thereof throughout a portion of said track, and other means for actuating said carrier along said portion thereof.
27. A heel-building machine having, in combination, a plurality of independent movable carriers on which heel lifts are superposed at a plurality of successive assembling stations, a supporting and guiding track therefor, means for actuating said carriers step by step through said assembling stations, and means for continuously actuating each carrier through another portion of the track.
28. A heel-building machine having, in combination, a plurality of independent movable carriers on which heel lifts are superposed at a plurality of successive assembling stations, a supporting and guiding track therefor, means for actuating said carriers step by step through said assembling stations, means including a plurality of concurrently operative members acting during

periods of rest of said step by step actuating means for supplying heel lifts one at a time to the respective carriers at their successive assembling stations, and other means for actuating each carrier through another portion of the track.

29. A heel-building machine having, in combination, a plurality of lift holders, a plurality of independent carriers upon which the lifts are successively superposed at a plurality of assembling stations, a track upon which the carriers travel, means including a plurality of concurrently operative picker members for intermittently transferring lifts from the respective holders to the respective carriers at their respective assembling stations, means for actuating said carriers step by step through their assembling stations, means for applying paste to the several lifts transferred, and means for actuating each carrier along another portion of the track.

30. A heel-building machine having, in combination, a plurality of movable carriers adapted to be actuated through successive stations, means for progressively assembling lifts upon said carriers at certain stations, means for positioning a previously formed heel block in registry with the completely assembled lifts at another station, and means for permanently uniting the completely assembled lifts and the heel block.

31. A heel-building machine having, in combination, a plurality of movable carriers adapted to be actuated through successive stations, means for progressively assembling lifts upon said carriers at certain stations, means for positioning a previously formed heel block in registry with the completely assembled lifts at another station, and means for nailing together said completely assembled lifts and said heel block at said last mentioned station.

32. A heel-building machine having, in combination, a plurality of movable carriers adapted to be actuated through successive stations, each carrier having means for gripping a projecting nail, means for progressively impaling lifts upon the nails of the several carriers, means for intermittently positioning previously formed heel blocks in registry with the completely assembled lifts impaled upon the nails at another station, and means for driving the nails from the carrier gripping means into said heel blocks at said last mentioned station to hold together the assembled lifts and the heel blocks.

33. A heel-building machine having, in combination, a plurality of movable carriers adapted to be actuated through successive stations, means for progressively assembling lifts upon said carriers at certain stations, means for intermittently positioning previously formed heel blocks at another sta-

tion, means for measuring the heights of the completely assembled lifts and the heel blocks, means for relatively moving said completely assembled lifts and said heel blocks into registry, and means for permanently uniting together said assembled lifts and said heel blocks.

34. A heel building machine having, in combination, a plurality of movable carriers adapted to be actuated through successive stations, means for progressively assembling lifts upon said carriers at certain stations, means for intermittently positioning previously formed heel blocks at another station, means for measuring the heights of the completely assembled lifts and the heel blocks, means for relatively moving said completely assembled lifts and said heel blocks into registry, means for permanently uniting together said assembled lifts and said heel blocks, and means dependent upon said measuring means for ejecting said completely assembled lifts and said heel blocks if the heights of either vary from predetermined amounts.

35. A heel-building machine having, in combination, a plurality of independent movable carriers adapted to be actuated step by step through successive stations, means for progressively assembling lifts upon said carriers at certain of said stations, means for intermittently uniting previously formed heel blocks to the lifts as they are completely assembled at another station, means for discharging the united heels, and means for successively returning the carriers vacated by the discharged heels to the initial station.

36. A heel-building machine having, in combination, means for automatically assembling a plurality of lifts to form a heel pile, and means for attaching said heel pile to a previously and extraneously formed heel block.

37. A heel-building machine having, in combination, means for intermittently supplying a plurality of previously and extraneously formed heel blocks, and means acting during periods of rest of said supplying means for automatically assembling heel piles and attaching them to the respective heel blocks.

38. A heel-building machine having, in combination, means for intermittently feeding a plurality of previously formed heel blocks, and means acting during each period of rest of said feeding means for concurrently and progressively assembling a plurality of heel piles, one heel pile being completed during each period of rest, and for attaching the completed heel pile to one of said heel blocks.

39. A heel-building machine having, in combination, means for progressively superposing a plurality of leather lifts to form a heel pile, means for intermittently sup-

plying a plurality of previously and extraneously assembled leatherboard heel blocks, means for registering said leather heel piles and said leatherboard blocks with 5 their breast edges in alignment, and means for securing together said heel piles and said blocks.

40. A heel-building machine having, in combination, means for supplying and supporting in definite position a previously and extraneously formed heel section comprising a plurality of lifts that are assembled with their breast edges in alignment, means for automatically assembling another heel 10 section of superposed lifts with their breast edges in substantial alignment, means for registering the two sections to produce a substantially plane breast surface, and means for attaching together said registered 15 sections.

41. A heel-building machine having, in combination a movable carrier for heel piles, nail-receiving and gripping means associated therewith, and means for supplying a nail 20 to said means.

42. A heel-building machine having, in combination, a carrier for heel piles movable into a nail-receiving position, means associated with said carrier for gripping a nail, 25 means disposed adjacent said carrier for positioning a nail with respect to said nail-gripping means, and means for forcing the nail in said positioning means into said nail-gripping means.

35. 43. A heel-building machine having, in combination, a plurality of movable carriers adapted to be actuated successively through a nail-loading station, nail-gripping means associated with each carrier, means for intermittently supplying nails in position adjacent each carrier as it passes through the nail-loading station, and means for intermittently forcing said nails into the gripping means of the successive carriers.

45. 44. A heel-building machine having, in combination, a plurality of lift holders, a plurality of movable carriers, means for transferring lifts from the respective lift-holders to positions below the respective carriers, and means for securing the transferred lifts to the under sides of the respective carriers.

55. 45. A heel-building machine having, in combination, a plurality of lift holders, a plurality of movable carriers, and means for transferring lifts from the respective lift holders and positively securing them to the respective carriers.

60. 46. A heel-building machine having, in combination, a plurality of lift holders, a plurality of movable carriers, a projecting member associated with each carrier, and means for transferring lifts from the respective lift-holders and impaling them

upon the projecting members of the respective carriers. 65

47. A heel-building machine having, in combination, a plurality of lift holders, a plurality of movable carriers, downwardly projecting members severally associated 70 with the respective carriers, means for concurrently transferring lifts from the respective lift-holders to positions below the respective carriers, and means for concurrently raising the transferred lifts and impaling them upon the downwardly projecting members of the respective carriers. 75

48. A heel-building machine having, in combination, a movable carrier having a nail associated therewith, means for laterally moving said carrier through an assembling station, and means for supplying a lift to said carrier at said assembling station and impaling it upon said nail. 80

49. A heel-building machine having, in combination, a movable carrier having a downwardly projecting nail associated therewith, means for actuating said carrier into an assembling station, means for supplying a lift below said carrier at said assembling station and means for raising said lift and forcibly impaling it upon said nail. 85 90

50. A heel-building machine having, in combination, a movable carrier, a nail-receiving and gripping means associated therewith, means for supplying a nail to said last means, and means for impaling a lift upon the nail held in said gripping means. 95

51. A heel-building machine having, in combination, a carrier movable into a nail-receiving position, means associated with said carrier for gripping a nail, means for forcing a nail into said gripping means, means for positioning a lift adjacent to 100 105 said carrier, and means for impaling said lift upon the nail gripped in said carrier.

52. A heel-building machine having, in combination, a movable carrier adapted to occupy a nail-receiving position and a lift-receiving position, means for supplying a nail to said carrier in said nail-receiving position, a stationary backing member disposed adjacent to said carrier in its lift-receiving position, means for positioning a lift adjacent to said carrier in its lift-receiving position, and means for forcing said lift and said carrier toward said backing member whereby said lift is impaled upon said nail. 110 115 120

53. A heel-building machine, having, in combination, a carrier having a nail projecting downwardly therefrom, a backing member disposed above said carrier and spaced therefrom, and means for raising said carrier against said backing member and impaling a lift upon said nail. 125

54. A heel-building machine having, in

combination, a movable carrier adapted to be actuated step by step through a plurality of assembling stations, a nail associated with said carrier and projecting therefrom, and

5 means for successively impaling lifts upon said nail in said assembling stations.

55. A heel-building machine having, in combination, a movable carrier adapted to be actuated step by step through a plurality 10 of assembling stations, a nail associated with said carrier and projecting therefrom, means for successively positioning lifts opposite the carrier in the several stations, and means for successively impaling said lifts 15 upon said nail.

56. A heel-building machine having, in combination, a plurality of movable carriers adapted to be actuated step by step through a plurality of assembling stations, each carrier 20 having a nail projecting therefrom, periodically operative means for concurrently positioning lifts opposite the carriers in the several stations, and periodically operative means for concurrently impaling 25 said lifts upon the nails of the respective carriers.

57. A heel-building machine having, in combination, a plurality of carriers adapted to occupy successive assembling stations, 30 each carrier having a nail projecting therefrom, periodically operative means for concurrently supplying single lifts adjacent to said carriers in the several stations, periodically operative means for concurrently impaling 35 said lifts upon the nails of the respective carriers, and means for successively and concurrently actuating the carriers and lifts secured thereto from one station to the next in intermittent steps whereby a plurality 40 of heels are concurrently assembled upon said carriers.

58. A heel-building machine having, in combination, means for feeding a succession of previously formed heel blocks, a carrier 45 upon which a pile of lifts is assembled, means for successively and laterally removing heel blocks from said feeding means, a carriage upon which the removed heel blocks are placed and which is adapted to travel in a direction parallel to said feeding means for positioning a heel block in registry with the pile of lifts, and means for attaching together the registered lifts and heel blocks.

59. A heel-building machine having, in combination, means for feeding a succession of previously formed heel blocks, a carrier upon which a pile of lifts is assembled, means for successively and laterally removing heel blocks from said feeding means, a carriage upon which the removed heel blocks are placed and which is adapted to travel in a direction parallel to said feeding means for positioning a heel block in 60 registry with the pile of lifts, means for

moving said registered pile of lifts and said heel block into engagement, and means for nailing together said lifts and heel block.

60. A heel-building machine having, in combination, a track, independent carriers adapted to travel thereon and upon which lifts are progressively assembled in superposed relation, a conveyer disposed at one side of said track for feeding a succession of previously formed heel blocks, a movable carriage adapted to reciprocate to and from said track in a direction parallel to said conveyer for moving heel blocks into registry with the completely assembled lifts 80 upon said carriers, a transverse conveyer for transferring the heel blocks upon said first conveyer to said carriage, and means for uniting the registered lifts and heel blocks to form a heel.

61. A heel-building machine having, in combination, a carrier adapted to have a pile of superposed lifts secured to the under side thereof, a movable carriage for positioning a previously formed wedge heel block beneath and in registry with said pile of lifts, means for tilting said carriage to cause the upper surface of said wedge heel block to cooperatively engage the lower surface of the pile of lifts, and means for securing 90 together said lifts and said tilted wedge heel block.

62. A heel-building machine having, in combination, a carrier adapted to have a pile of superposed lifts secured to the under side thereof, a movable carriage for positioning a previously formed heel block beneath and in registry with said pile of lifts, means for raising said carriage to bring said heel block into engagement with 100 said pile of lifts and for exerting a positive pressure thereon, and means for nailing together said lifts and said heel block.

63. A heel-building machine having, in combination, a carrier having a pointed member projecting downwardly therefrom, a reciprocating plunger disposed beneath said carrier and normally spaced therefrom, means for interposing a lift between said carrier and said plunger, means for raising said plunger to impale said lift upon said pointed member and for subsequently lowering said plunger, and means for temporarily supporting said lift during the initial lowering of said plunger.

64. A heel-building machine having in combination, a carrier having a pointed member projecting downwardly therefrom, a reciprocating plunger disposed beneath said carrier and normally spaced therefrom, means for interposing a lift between said carrier and said plunger, means for vertically reciprocating said plunger to impale the lift upon said pointed member, and a supporting finger laterally movable beneath 125

the impaled lift just prior to the downward movement of said plunger for preventing the withdrawal of the lift from said pointed member.

to be forced across said surface by the actuation of said plunger. 65

- 5 65. A heel-building machine having, in combination, a plurality of spaced downwardly projecting pointed members, a reciprocable plunger disposed beneath said pointed members, means for concurrently interposing lifts between the respective pointed members and said plunger, a paste pot into which said plunger is immersed, means for vertically reciprocating said plunger whereby paste is applied to the under sides of said lifts and said lifts are impaled upon said pointed members, and a plurality of laterally slid able fingers that are temporarily inserted beneath the impaled lifts just prior to the downward movement of said plunger to prevent the withdrawal of said lifts from said pointed members.

- 20

70. A shoe machine having, in combination, a downwardly projecting pointed member, means for positioning a blank beneath said member, a paste-containing tank, a vertically reciprocable plunger adapted to be immersed therein for engaging said blank and impaling it upon said pointed member, cams disposed near the ends of said tank, and a paste-scraping member cooperating with said cams and adapted to engage and be forced across the upper surface of said plunger during the reciprocating operation thereof.

66. A heel-building machine having, in combination, a carrier adapted to be moved through a plurality of assembling stations in which lifts are successively positioned beneath said carrier, and means for applying paste to the underside of each lift and successively superposing and securing said lifts to the underside of said carrier.

71. A lift holder having, in combination, 80
heel and breast members between which the
lifts are stacked, a pivotally mounted gate
associated with one of said members for per-
mitting the removal of but one lift at a time,
and cooperating adjustable guide arms asso- 85
ciated with said member for laterally posi-
tioning the lifts before their removal.

67. A heel-building machine having, in combination, a carrier adapted to be moved through a plurality of assembling stations, a pointed member associated with said carrier and projecting therefrom, means for successively positioning lifts beneath said carrier in the successive assembling stations, and a reciprocable pasting plunger disposed beneath said assembly stations and adapted to apply paste to said lifts and impale them upon said pointed member.

72. A lift holder having, in combination, means for containing a stack of superposed lifts, reciprocating means for laterally removing the bottom lifts therefrom, and a pivotally mounted gate associated with one end of said containing means for permitting the lateral removal of but a single lift at a time. 90

68. A heel-building machine having, in combination, a movable carrier, having a nail associated therewith and projecting downwardly therefrom, a backing member disposed above said carrier and spaced therefrom, a reciprocable pasting member disposed below and normally spaced from said carrier, means for interposing a lift between the carrier and said pasting member, and means for causing said pasting member to apply paste to said lift and to force said lift and said carrier toward said backing member, whereby said lift is impaled upon said nail.

73. A lift holder having, in combination, means for containing a stack of lifts, and a gate pivotally mounted at both ends to permit of independent pivotal movements thereof.

69. A shoe machine having, in combination, a downwardly projecting pointed member, means for supplying a blank beneath said member, a paste-containing tank, 60 a vertically reciprocable plunger adapted to be immersed therein for engaging said blank and impaling it upon said pointed member, and a paste-scraping member adapted to engage the upper surface of said plunger and

74. A lift holder having, in combination, means for containing a stack of lifts, and co-operating guide arms adjustably and rigidly associated with one end of said containing means for laterally positioning the lifts disposed in that end thereof. 105

combination, a movable carrier, having a nail associated therewith and projecting downwardly therefrom, a backing member disposed above said carrier and spaced therefrom, a reciprocable pasting member disposed below and normally spaced from said carrier, means for interposing a lift between the carrier and said pasting member, and means for causing said pasting member to apply paste to said lift and to force said lift and said carrier toward said backing member, whereby said lift is impaled upon said nail.

75. A heel-building machine having, in combination, a lift-holder, a sliding picker member having means for positively gripping a lift in said lift-holder and adapted to remove the lift laterally therefrom, said gripping means being loosely associated with said picker member, and means for raising said gripping means and lift held thereby above the plane of said picker member. 115

69. A shoe machine having, in combination, a downwardly projecting pointed member, means for supplying a blank beneath said member, a paste-containing tank, 60 a vertically reciprocable plunger adapted to be immersed therein for engaging said blank and impaling it upon said pointed member, and a paste-scraping member adapted to engage the upper surface of said plunger and

76. A heel-building machine having, in combination, a lift-holder adapted to contain stacked lifts, a movable carrier adapted to occupy a station to one side of said lift holder, a sliding picker member having articulated grippers for positively gripping the lateral edges of the lowermost lift in said lift-holder for transferring said lift to said station, and means for positively securing the transferred lift to said carrier. 120 125

77. A heel-building machine having, in combination, a movable carrier, means for

actuating said carrier step by step through successive stations, means for progressively assembling lifts upon said carrier in certain of said stations, and means for measuring 5 the assembled lifts.

78. A heel-building machine, in combination, a movable carrier, means for actuating said carrier step by step through successive stations, means for positively locking said 10 carrier in certain stations, means for progressively assembling lifts upon said carrier in said certain stations, and means for measuring the height of the assembled lifts in another station.

79. A heel-building machine having, in combination, a movable carrier adapted to be actuated through successive stations, means for positioning a laterally projecting nail upon said carrier in the first station, 15 means for progressively impaling lifts upon said nail in a plurality of succeeding stations, and means for measuring the height of said impaled lifts in another station.

80. A heel-building machine having, in combination, relatively movable carriers for 20 severally carrying piles of superposed lifts, means for measuring the heights of said piles of superposed lifts, means for relatively moving said carriers to bring the respective piles of superposed lifts into 25 registry, and means for uniting together said piles of lifts.

81. A heel-building machine having, in combination, a movable carrier for carrying 30 a pile of superposed lifts, a second movable carrier for carrying a heel block of polygonal plan, means for separately measuring said pile of superposed lifts and said heel block, means for relatively moving said pile 35 of lifts and said heel block into registry, means for nailing together said registered lifts and heel block, and means dependent upon the measuring means for ejecting said lifts and heel block if either varies from 40 predetermined dimensions.

82. A heel-building machine having, in combination, a plurality of movable carriers for severally supporting and intermittently actuating piles of superposed lifts, and 45 means acting during periods of rest of said carriers for concurrently measuring the respective piles of superposed lifts.

83. A heel-building machine having, in combination, means for supplying heel piles 50 and heel blocks, means for concurrently measuring one of said heel piles and one of said heel blocks, and means responsive to said concurrent measurements for ejecting said heel block if either vary from predetermined dimensions.

84. A heel-building machine having, in combination, means for supplying heel piles and heel blocks, means for concurrently measuring one of said heel piles and one of 55 said heel blocks, means responsive to said

concurrent measurements for ejecting said heel block if either vary from predetermined dimensions, and means for positioning said heel pile and said heel block in registry if the measurements are correct and 70 for attaching them together to form a complete heel.

85. A heel-building machine having, in combination, means for feeding heel piles and heel blocks through separate measuring 75 stations and into registry in a nailing station, means for concurrently measuring one of said heel piles and one of said heel blocks in the respective measuring stations, ejecting means responsive to said measuring means 80 and operative if the heel pile or the heel block measured vary from predetermined dimensions for discharging said heel block, means for nailing together said heel pile and said heel block if the concurrent measurements are correct, and means for rendering inoperative said nailing means if said measurements are incorrect.

86. A heel-building machine having, in combination, means for positioning in registry a plurality of sections of a heel, means for nailing together said sections, and means for rendering said nailing means inoperative during the continued operation of the 90 machine.

87. A heel-building machine having, in combination, a plurality of separate supports for sections of a heel, means for independently moving said supports to bring said sections into registry, means for attaching together said sections to form a heel, and means dependent upon the height 100 of said separate sections for preventing the operation of said attaching means.

88. A heel-building machine having, in combination, a plurality of separate supports for sections of a heel, means for moving said supports to bring said sections into registry one above the other, means for raising the lower support to bring the heel 110 section thereon into engagement with the other heel section, and means for nailing together said sections to form a heel.

89. A heel-building machine, having, in combination, a plurality of separate supports for sections of a heel, means for moving said supports to bring said sections into registry one above the other, means for raising the lower support to bring the heel section thereon into engagement with the other heel section, means for positively locking said support in its raised position, and means for nailing together said sections to 115 form a heel.

90. A heel-building machine having, in combination, means for supporting a pile 125 of superposed lifts, means for positioning a previously formed heel block in registry with said pile of lifts at a nailing station, and means for nailing together said pile of 130

lifts and said heel block and for subjecting them to pressure at said station.

91. A heel-building machine having, in combination, means for supporting a pile of 5 superposed lifts and a heel-block in registry, means for attaching together said pile and said block and for subjecting them to positive pressure, and adjustable means for varying the positive pressure to which the 10 pile and block are subjected.

92. A heel-building machine having, in combination, a plurality of lift magazines, means for removing lifts therefrom and assembling them in the form of a heel pile, 15 and means for attaching said heel pile to an extraneously formed heel block.

93. A heel-building machine having, in combination, means for holding a supply of lifts, means acting periodically for removing lifts therefrom and assembling them in the form of heel piles, means for intermittently supplying a plurality of extraneously formed heel blocks, and means for attaching the successive heel piles to the 25 respective heel blocks.

94. A heel-building machine having, in combination, a plurality of separate supports for sections of a heel, means for independently moving said supports to bring 30 said sections into registry at a predetermined station, and means at said station for nailing together said sections to form a heel.

95. A heel-building machine having, in combination, means for supporting a row 35 of spaced lifts in edge to edge relation, a plurality of spaced pointed members disposed above said supporting means, and means for effecting relative movement between said supporting means and said 40 pointed members whereby said row of lifts is impaled upon said members.

96. A heel-building machine having, in combination, means for supporting a row 45 of lifts, carrying means movable from one station to another having a plurality of projecting pointed members, means for transferring lifts from said supporting means to positions beneath said carrying 50 means, and means for impaling said lifts upon the pointed members of said carrying means.

97. A heel-building machine having, in combination, means for holding a plurality 55 of lifts, carrying means movable from one station to another and comprising downwardly projecting pointed members, means for concurrently transferring a series of lifts from said holding means to positions beneath 60 said carrying means, and means for concurrently impaling the transferred lifts upon the pointed members of said carrying means.

98. A heel-building machine having, in combination, a movable carrier having a

relatively fixed pointed member associated therewith, means for actuating said carrier from one station to another, a holder adapted to contain a stack of lifts, and means for removing a lift from said holder and 70 supplying it to said carrier at one of its stations and impaling it upon said pointed member.

99. A heel-building machine having, in combination, means for supporting a row 75 of lifts, means disposed parallel to said row of lifts comprising a series of pointed members, a plurality of means disposed in side by side relation for transferring said row of lifts from said supporting means to 80 positions beneath said pointed members, and means for impaling said transferred lifts upon said pointed members.

100. A heel-building machine having, in combination, a plurality of spaced downwardly projecting pointed members, a reciprocable means disposed beneath said pointed members, means for concurrently interposing lifts between the respective pointed members and said reciprocable 90 means, means for applying paste to said reciprocable means, and means for vertically reciprocating said reciprocable means to cause it to engage and apply paste to the under sides of said lifts and to impale them 95 upon said pointed members.

101. A heel-building machine having, in combination, a movable carrier adapted to occupy a station in which a lift is positioned beneath it, and means for applying paste 100 to the underside of said lift and then securing said lift to the underside of said carrier.

102. A heel-building machine having, in combination, a heel-building device having 105 a pointed member projecting therefrom, means for producing a lift in position adjacent said device, and means for applying paste to the side of the lift removed from said device and then impaling the lift upon 110 said pointed member.

103. A heel-building machine having, in combination, a carrier having a pointed member projecting therefrom, means supporting a lift in position beneath said carrier with its underside exposed, and means for engaging the exposed underside of said lift, applying paste thereto, raising the supporting means and lift, and impaling the lift upon said pointed member. 115

104. A heel-building machine having, in combination, a movable carrier adapted to be actuated through successive stations, means for positioning a laterally projecting nail upon the carrier at one station, means 125 for progressively impaling lifts upon said nail at a plurality of succeeding stations, and means for ejecting said nail and impaled lifts from said carrier at another station.

105. A heel-building machine having, in 130

combination, a movable carrier for supporting a pile of lifts including a wedge lift, means for moving said carrier and lifts into a predetermined station, and means at said 5 station for tilting said carrier and lifts to cause the upper surface of the pile of lifts to occupy a substantially horizontal position.

106. A heel-building machine having, in combination, a movable carrier for supporting a pile of lifts having its upper surface inclined to the horizontal, means for tilting said carrier and lifts to bring the upper surface of the pile of lifts into a horizontal 15 plane, and means for depositing other lifts upon the horizontal upper surface of said pile of lifts.

107. A heel-building machine having, in combination, means for assembling a plurality of lifts in superposed relation, means for measuring the height of said superposed lifts, and means dependent upon said measuring means for ejecting said superposed lifts.

108. A heel-building machine having, in combination, means for assembling a plurality of lifts sufficient to form a complete heel, means for measuring the height of the heel when partially completed, and means 30 for discharging the partially completed heel in accordance with the action of said measuring means.

109. A heel-building machine having, in combination, means for assembling a plurality of lifts to form a heel, means for nailing together said lifts and heel-measuring means for preventing the nailing operation under predetermined conditions.

110. A heel-building machine having, in combination, means for assembling a plurality of lifts to form a heel, means for nailing together said lifts, and means dependent upon the height of said heel for preventing the nailing operation and ejecting the 45 unnailed heel.

111. A heel-building machine having, in combination, means for assembling a plurality of lifts to form a heel and for delivering said heel to a nailing station, means 50 for nailing together said lifts, means dependent upon the height of the heel for controlling the operation of said nailing means, means for transferring a nailed heel to a point of delivery, and means for ejecting 55 an unnailed heel.

112. A heel-building machine having, in combination, means for periodically assembling and alining a plurality of lifts to form heels, means periodically operative to nail 60 together said heels, and means dependent upon the height of each heel for preventing the nailing operation during the continued operation of the assembling and alining means.

113. A heel machine having, in combina-

tion, a plurality of unconnected carriers for supporting heel-piles, each adapted for independent movement, and means for actuating certain of said carriers in one manner and concurrently actuating another carrier 70 in a different manner.

114. A heel machine having, in combination, a plurality of unconnected carriers for supporting heel-piles, each adapted for independent movement, an endless supporting track for said carriers, and means for actuating certain of said carriers in steps throughout a portion of said track and for concurrently and continuously actuating another carrier throughout another portion of 80 said track.

115. A heel machine having, in combination, a plurality of unconnected carriers for supporting and carrying heel-piles, each adapted for independent movement, and 85 means for actuating a portion of said carriers at one rate of speed and at the same time actuating another portion of said carriers at a different rate of speed.

116. A shoe machine having, in combination, a downwardly projecting pointed member, means for supporting a blank beneath said member, and a paste-applying member adapted to engage said blank and impale it 90 upon said pointed member.

117. A shoe machine having, in combination, a downwardly projecting pointed member, means for supporting a blank beneath said member, a paste-applying member adapted to engage said blank and impale it 100 upon said pointed member, and means for removing the excess paste from said paste-applying member.

118. A heel-building machine having, in combination, means for assembling in superposed relation a plurality of lifts and a previously formed heel section, and means for securing together said assembled lifts and section to form a heel.

119. A heel-building machine having, in combination, means for supplying lifts and previously formed heel sections, means for assembling a plurality of lifts and a base section in superposed relation, and means for nailing together said assembled lifts and base section.

120. A heel-building machine having, in combination, a movable carrier having a relatively fixed pointed member associated therewith, means for actuating said carrier 120 from one station to another, reciprocatory means movable towards and from said pointed member, and means for interposing lifts between said reciprocatory means and said pointed member, whereby said lifts are 125 impaled upon said pointed member.

121. A heel-building machine having, in combination, means for holding a downwardly projecting nail, means for progressively impaling lifts in superposed relation 130

upon said nail, and means for ejecting said nail and lifts impaled thereon.

122. A heel-building machine having, in combination, lift holding means, movable lift receiving means provided with a plurality of pointed members, means for actuating said movable lift receiving means through a plurality of stations, and means at each station for transferring lifts from said holding means and impaling them upon said pointed members of said lift receiving means, whereby a plurality of heels are built.

123. A heel-building machine having, in combination, a plurality of lift holders, a corresponding number of lift receiving devices each provided with a downwardly projecting pointed member, means for effecting relative movement between said lift holders and said lift receiving devices to position said lift receiving devices and said lift holders successively in adjacent relation at a plurality of stations, and means disposed at said stations for transferring lifts from said lift holders and impaling them upon the pointed members of said lift receiving devices, whereby a plurality of heels are built.

124. A heel-building machine having, in combination, a row of lift holders, a corresponding row of lift receiving devices disposed substantially parallel thereto and each provided with a pointed member, means for actuating said row of lift receiving devices in steps with respect to said lift holders to position the respective devices adjacent the respective lift holders successively, means cooperating with each lift holder for transferring lifts to positions adjacent said pointed members of said lift receiving devices, and means for impaling said lifts upon said pointed members, whereby a plurality of heels are built.

125. A heel-building machine having, in combination, lift holding means, lift receiving means provided with a plurality of pointed members, means for effecting relative movements of said lift holding means and said lift receiving means through a plurality of stations, and means for transferring a plurality of lifts from said holding means, impaling said lifts upon the said pointed members and applying paste to said lifts at each station, whereby a plurality of heels are progressively assembled upon said pointed members.

126. A heel-building machine having, in combination, a row of lift holders, a corresponding row of lift receiving devices disposed substantially parallel thereto and each provided with a pointed member, means for actuating said row of lift receiving devices in steps with respect to said lift holders to position the respective devices ad-

jacent the respective lift holders successively, a plurality of transfer devices severally adapted to reciprocate between said lift holders and said lift receiving devices for carrying a plurality of lifts from the lift holders to positions beneath the pointed members of said lift receiving devices, and means for raising the transfer devices and lifts thereon and impaling them upon said pointed members, whereby a plurality of heels are built.

127. A heel-building machine having, in combination, means for assembling a plurality of lifts in superposed relation, means for measuring the height of the heel thus formed, heel pressing means, and means dependent on the measuring means for determining whether or not the heel is to be pressed.

128. A heel-building machine having, in combination, means for assembling a plurality of lifts in superposed relation, heel pressing means, heel measuring means, means for moving the heel to the heel pressing means, and means dependent on the indication of the measuring means to cause the heel to be pressed or to pass beyond said pressing means unpressed.

129. A heel-building machine having, in combination, a movable heel carrier, means for actuating said carrier step by step through a plurality of stations including a heel pressing station, means for assembling a plurality of lifts on said carrier, means for ejecting the heel thus assembled, and means controlled by the height of the heel for determining whether or not the heel is to be ejected at the pressing station.

130. A heel-building machine having, in combination, a heel carrier constructed and arranged to hold a projecting pointed member, means for actuating said carrier step by step through a plurality of stations including a heel pressing station, means for successively impaling a plurality of lifts on said pointed member, and devices controlled by the height of the heel while still on said pointed member for determining whether or not the heel is to be pressed.

131. A heel-building machine having, in combination, a heel carrier constructed and arranged to hold a projecting pointed member, means for successively impaling a plurality of lifts on said pointed member, heel pressing means, means for actuating said carrier to advance it to said heel pressing means, and means controlled by the height of the heel on said pointed member for effecting the heel pressing operation.

132. A heel-building machine having, in combination, a heel building device constructed and arranged to sustain an impaling member which projects from its heel holding face, a plurality of magazines

- adapted to contain stacks of lifts, means intermediate said magazines and device movable to place lifts taken from the successive magazines in position facing said device, 5 and mechanism for causing periodic relative movements between said means and device to successively impale said lifts on said member in superposed relation and form a heel or heel section.
- 10 133. A heel-building machine having, in combination, a heel carrier movable through a series of lift receiving stations to a heel delivery station constructed and arranged to sustain a downwardly projecting pointed member, means for successively positioning lifts below said carrier at the receiving stations, mechanism for successively impaling said lifts on said pointed member in face to face relation to form a heel or heel section, 15 and means for ejecting the completed article at the delivery station.
134. A heel-building machine having, in combination, a heel building device constructed and arranged to sustain a projecting pointed member upon which lifts may be impaled, a series of lift holding magazines, means for transferring lifts from said magazines and for impaling them successively on said member in face to face relation to build a heel or heel section, and means for ejecting the completed article. 20
135. A heel-building machine having, in combination, a heel-building device constructed and arranged to sustain a projecting pointed member upon which lifts may be impaled, means for impaling lifts successively on said member in face to face relation to build a heel or heel section, and means for measuring the height of the article thus produced. 25
136. A heel-building machine having, in combination, a heel carrier constructed and arranged to hold a pointed member which projects from its heel holding face, means for impaling lifts successively on said member in face to face relation, and means for applying paste between the lifts to secure them together and form a heel or heel section. 30
- 50 137. A heel-building machine having, in combination, a movable carrier constructed and arranged to hold a projecting lift impaling member, means for actuating said carrier through a plurality of stations, reciprocatory means at each station movable toward and from said impaling member, and means for interposing lifts between said reciprocatory means and said carrier, whereby said lifts are successively impaled on said member to form a heel or heel section. 35
138. A heel-building machine having, in combination, means for assembling heel lifts to form a heel, heel nailing mechanism, means for measuring the height of the heel, 40 and means dependent upon said measuring
- means for determining whether or not the heel is to be nailed.
139. A heel-building machine having, in combination, a movable heel carrier, means for assembling a plurality of lifts in superposed relation on said carrier, means for engaging the free end of the heel sustained on said carrier to measure its height, and means dependent on said measuring means for ejecting the heel from the heel carrier. 45
140. A heel-building machine having, in combination, a movable heel carrier for advancing a succession of heels, means for successively engaging the free ends of the heels sustained on the carrier to measure their several heights, heel nailing mechanism, heel ejecting mechanism, and means dependent on said measuring mechanism to determine which of said nailing or ejecting mechanisms shall operate on the heel. 50
141. A heel-building machine having, in combination, a movable lift carrier adapted to occupy a lift receiving station, means for moving a lift laterally to a position beneath said carrier, means for securing said lift to the under side of said carrier, and means for pasting the under side of the lift. 55
142. A heel-building machine having, in combination, a movable lift carrier adapted to occupy a lift receiving station and a heel delivering station, means for successively moving lifts laterally to a position beneath said carrier, securing them in superposed relation on the underside of the carrier, and pasting the under sides thereof, and means for discharging the heel thus assembled from the carrier at the delivering station. 60
143. A heel-building machine having, in combination, a movable carrier adapted to occupy a station in which a lift is positioned beneath it, and means for securing said lift to the under side of said carrier and for applying paste to only the exposed face of the lift as it is sustained by said carrier. 65
144. A heel-building machine having, in combination, a heel building device adapted to receive and sustain a plurality of lifts, means for successively positioning lifts beneath said device, and means for securing said lifts successively in a superposed pile to the under side of said device and applying paste to one of the two contacting surfaces of adjacent lifts in the pile. 70
145. A heel-building machine having, in combination, a heel carrier adapted to receive and sustain a heel formed of a plurality of lifts, means for successively positioning lifts in a superposed pile beneath said carrier and for securing said lifts to the under side of said carrier, and means for moving said carrier and heel to a delivering station. 75
146. A heel-building machine having, in combination, a plurality of lift holders, a heel carrier movable step by step past said

holders, means for successively transferring lifts from said holders to said carrier during its periods of rest, said lifts being advanced from the holders breast foremost, and a 5 gaging surface against which the breasts of the successively delivered lifts are aligned in superposed relation.

147. A heel-building machine having, in combination, a heel carrier and a series of 10 lift holders relatively movable to cause the carrier to successively occupy a position opposite each holder, means for transferring a lift from each holder to the carrier in succession, said lifts being advanced from the 15 holders breast foremost, and a breast gage against which the lifts are successively delivered in superposed relation.

148. A heel-building machine having, in combination, a heel carrier and a series of 20 lift holders relatively movable to cause the carrier to successively occupy a position opposite each holder, means for transferring a lift from each holder to the carrier in succession, said lifts being advanced from the 25 holders breast foremost, a breast gage against which the lifts are successively delivered in superposed relation, and means for pressing the superposed pile of lifts while on the carrier.

30 149. A heel-building machine having, in combination, a heel carrier and a series of lift holders relatively movable to cause the carrier to successively occupy a position opposite each holder, means for transferring a lift from each holder to the carrier in succession, said lifts being advanced from the 35 holders breast foremost, a breast gage against which the lifts are successively delivered in superposed relation, means for 40 pressing the superposed pile of lifts while on the carrier, and means for ejecting the pressed heel from the carrier.

150. A heel-building machine having, in combination, means for assembling a plurality of lifts to form a heel, mechanism for nailing said lifts together, and means for delivering the nailed heel comprising a traveling conveyer in the form of an endless belt arranged in a vertical plane, one run at 45 least of which is above the heel, provided with a depending finger for engaging the

lateral surface of the heel and carrying it forward beneath the conveyer.

151. A heel-building machine having, in combination, means for forming a succession 55 of heels, and a conveyer above the heels comprising an endless belt intermittently movable and provided with a plurality of spaced depending fingers for successively engaging the several heels and pushing them out of 60 the machine.

152. A heel-building machine having, in combination, a series of lift holders, continually operating heel lift assembling, nailing and delivering mechanism including an endless 65 conveyer provided with a plurality of depending fingers to successively engage the heels by their lateral surfaces and remove them from the machine after having been nailed, and means for imparting a step by 70 step movement to said conveyer.

153. A heel-building machine having, in combination, heel assembling and delivering mechanism operating to produce a succession of heels, and including an endless conveyer 75 provided with a plurality of depending fingers to successively engage the heels by their lateral surfaces and remove them from the machine, heel nailing mechanism, means for advancing said conveyer step by 80 step, and means for nailing the heels during periods of rest of the conveyer.

154. In a heel-building machine, picker mechanism for transferring lifts comprising side arms articulately connected and provided 85 with means for engaging both the edge and margin of the lift near each breast corner.

155. In a heel-building machine, picker mechanism for transferring lifts comprising side arms yieldingly urged toward each other 90 and provided with abutments for engaging the opposite edges of the lift and with adjacent knife edges for engaging the face of the lift.

156. In a heel-building machine, picker 95 mechanism for transferring lifts comprising side arms constructed and arranged to grip the lift at its opposite side edges and support the lift during its transferral, and a spring engaging said arms for urging them together. 100

ERASTUS E. WINKLEY.

Certificate of Correction.

It is hereby certified that in Letters Patent No. 1,447,369, granted March 6, 1923, upon the application of Erastus E. Winkley, of Lynn, Massachusetts, for an improvement in "Heel-Building Machines," errors appear in the printed specification requiring correction as follows: Page 4, line 129, for the word "on" read *an*; page 9, line 21, for the word "springs" read *spring*; page 10, line 39, for the word "side" read *size*, and line 60, for "magazine" read *magazines*; page 27, line 41, claim 19, after the word "actuating" insert the word *each*; same page and claim, line 45, and line 58, claim 20, for the word "portions" read *portion*; page 29, line 94, claim 50, strike out the article "a", second occurrence; and that the said Letters Patent should be read with these corrections therein that the same may conform to the record of the case in the Patent Office.

Signed and sealed this 17th day of April, A. D., 1923.

[**SEAL.**]

KARL FENNING,
Acting Commissioner of Patents.
